PIXEL CIRCUIT, DISPLAY PANEL AND
DISPLAY APPARATUS

The present application is a US National Stage of International Application No. PCT/CN2020/123332, filed on Oct. 23, 2020, and entitled 'PIXEL CIRCUIT, DISPLAY PANEL AND DISPLAY APPARATUS', the entire contents of which are incorporated herein by reference.

FIELD

The present disclosure relates to the technical field of display, in particular to a pixel circuit, a display panel and a display apparatus.

BACKGROUND

An organic light emitting diode (OLED), a quantum dot light emitting diode (QLED), a micro light emitting diode (micro LED) and other electroluminescent diodes have the advantages of self-luminescence, low energy consumption, etc., and are one of the hotspots in the field of display apparatus application research nowadays. Pixel circuits are commonly used to drive electroluminescent diodes to emit light. In practical applications, when a display apparatus is to display any gray scale within the gray scale range, the data voltage may be made to exceed the output range of a driver integrated circuit (IC), resulting in the problem that the dark state is not sufficiently dark, which affects the contrast of the display apparatus.

SUMMARY

An embodiment of the present disclosure provides a pixel circuit, including:

a data writing transistor, where a gate of the data writing transistor is electrically connected with a first scan line, a first electrode of the data writing transistor is electrically connected with a data line, a second electrode of the data writing transistor is electrically connected with a first electrode of a drive transistor, and a material of an active layer of the data writing transistor is a low temperature poly-silicon material;

a threshold compensation transistor, where a gate of the threshold compensation transistor is electrically connected with a second scan line, a first electrode of the threshold compensation transistor is electrically connected with a gate of the drive transistor, a second electrode of the threshold compensation transistor is electrically connected with a second electrode of the drive transistor, and a material of an active layer of the threshold compensation transistor is a metal oxide semiconductor material;

a compensation circuit, electrically connected with the gate of the drive transistor; and

a light emitting control circuit, electrically connected with a first power end, the first electrode and the second electrode of the drive transistor and a first electrode of a light emitting device, and configured to turn on the first power end and the first electrode of the drive transistor and turn on the second electrode of the drive transistor and the first electrode of the light emitting device under control of a signal of a light emitting control line to drive the light emitting device to emit light.

In some examples, the compensation circuit is configured to compensate for a voltage of the gate of the drive transistor according to a parasitic capacitor.

2

In some examples, the compensation circuit includes: a first compensation capacitor; and

a first electrode of the first compensation capacitor is electrically connected with the gate of the drive transistor, and a second electrode of the first compensation capacitor is electrically connected with the first scan line.

In some examples, the parasitic capacitor includes a channel capacitor between the gate and the first electrode of the threshold compensation transistor.

10 In some examples, a capacitance value of the channel capacitor between the gate and the first electrode of the threshold compensation transistor is a first channel capacitance value, and a difference between a capacitance value of the first compensation capacitor and the first channel capacitance value satisfies $0\pm\Delta c1$.

In some examples, the compensation circuit includes: a first compensation control transistor; and

20 a gate of the first compensation control transistor is electrically connected with the first scan line, and a first electrode and a second electrode of the first compensation control transistor are electrically connected with the gate of the drive transistor.

In some examples, the parasitic capacitor includes the 25 channel capacitor between the gate and the first electrode of the threshold compensation transistor, and the capacitance value of the channel capacitor between the gate and the first electrode of the threshold compensation transistor is the first channel capacitance value;

30 a capacitance value of a channel capacitor between the gate and the first electrode of the first compensation control transistor is a second channel capacitance value, a capacitance value of a channel capacitor between the gate and the second electrode of the first compensation control transistor is a third channel capacitance value, and a sum of the second channel capacitance value and the third channel capacitance value is a total channel capacitance value; and

35 a difference between the total channel capacitance value and the first channel capacitance value satisfies $0\pm\Delta c2$.

40 In some examples, the compensation circuit includes: a second compensation control transistor; and

45 a gate of the second compensation control transistor is electrically connected with the first scan line, a first electrode of the second compensation control transistor is electrically connected with the gate of the drive transistor, and a second electrode of the second compensation control transistor is in suspended connection.

In some examples, the parasitic capacitor includes the 50 channel capacitor between the gate and the first electrode of the threshold compensation transistor, and the capacitance value of the channel capacitor between the gate and the first electrode of the threshold compensation transistor is a first channel capacitance value;

55 a capacitance value of a channel capacitor between the gate and the first electrode of the second compensation control transistor is a fourth channel capacitance value; and

60 a difference between the fourth channel capacitance value and the first channel capacitance value satisfies $0\pm\Delta c3$.

In some examples, the compensation circuit includes: a second compensation capacitor; and

65 a first electrode of the second compensation capacitor is electrically connected with the gate of the drive transistor, and a second electrode of the second compensation capacitor is electrically connected with the first electrode of the light emitting device.

In some examples, the pixel circuit further includes: a first reset transistor; and

a gate of the first reset transistor is electrically connected with a first reset line, a first electrode of the first reset transistor is electrically connected with an initialization signal line, and a second electrode of the first reset transistor is electrically connected with the gate of the drive transistor.

In some examples, a material of an active layer of the first reset transistor is a metal oxide semiconductor material.

In some examples, the pixel circuit further includes: a second reset transistor; and

a gate of the second reset transistor is electrically connected with a second reset line, a first electrode of the second reset transistor is electrically connected with the initialization signal line, and a second electrode of the second reset transistor is electrically connected with the first electrode of the light emitting device.

In some examples, a pixel circuit includes: a first light emitting control transistor, a second light emitting control transistor and a storage capacitor;

a gate of the first light emitting control transistor is electrically connected with the light emitting control line, a first electrode of the first light emitting control transistor is electrically connected with the first power end, and a second electrode of the first light emitting control transistor is electrically connected with the first electrode of the drive transistor;

a gate of the second light emitting control transistor is electrically connected with the light emitting control line, a first electrode of the second light emitting control transistor is electrically connected with the second electrode of the drive transistor, and a second electrode of the second light emitting control transistor is electrically connected with the first electrode of the light emitting device; and

a first electrode of the storage capacitor is electrically connected with the first power end, and a second electrode of the storage capacitor is electrically connected with the gate of the drive transistor.

An embodiment of the present disclosure provides a display panel, including:

a base substrate, where the base substrate includes a plurality of sub-pixels, where each of the plurality of sub-pixels comprise a pixel circuit, and the pixel circuit comprises a first compensation capacitor and a drive transistor;

a first conductive layer, located on the base substrate, and including a first scan line and a gate of the drive transistor, where one row of sub-pixels corresponds to one first scan line;

a first interlayer dielectric layer, located on a side, facing away from the base substrate, of the first conductive layer;

a second conductive layer, located on a side, facing away from the base substrate, of the first interlayer dielectric layer, and including compensation conductive parts; where the sub-pixels include the compensation conductive parts; and for the same sub-pixel, the compensation conductive part is electrically connected with the gate of the drive transistor, and

for the first scan line and the compensation conductive part corresponding to the same sub-pixel, an orthographic projection of the first scan line on the base substrate and an orthographic projection of the compensation conductive part on the base substrate have a first overlapping region, the first compensation capacitor is located in the first overlapping region, and the first compensation capacitor is formed by an overlapping portion between the first scan line and the compensation conductive part.

In some examples, for the first scan line and the compensation conductive part corresponding to the same sub-pixel, the orthographic projection of the first scan line on the base

substrate covers the orthographic projection of the compensation conductive part on the base substrate.

In some examples, the pixel circuit further includes a threshold compensation transistor; and the display panel further includes:

a second interlayer dielectric layer, located on a side, facing away from the base substrate, of the second conductive layer;

an oxide semiconductor layer, located on a side, facing 10 away from the base substrate, of the second interlayer dielectric layer, and including an active layer of the threshold compensation transistor;

a second gate insulating layer, located on a side, facing 15 away from the base substrate, of the oxide semiconductor layer; and

a third conductive layer, located on a side, facing away from the base substrate, of the second gate insulating layer, and including a second scan line; where one row of sub-pixels corresponds to one second scan line; where

20 for the second scan line and the threshold compensation transistor corresponding to the same sub-pixel, an orthographic projection of the active layer of the threshold compensation transistor on the base substrate and an orthographic projection of the second scan line on the base

25 substrate have a second overlapping region; a first part of capacitor of a channel capacitor of the threshold compensation transistor is located in the second overlapping region; and the first part of capacitor is formed by an overlapping portion between the second scan line and the active layer of the threshold compensation transistor.

In some examples, the second conductive layer further includes an auxiliary scan line, where one row of sub-pixels corresponds to one auxiliary scan line;

for the auxiliary scan line and the threshold compensation 35 transistor corresponding to the same sub-pixel, an orthographic projection of the auxiliary scan line on the base substrate and the orthographic projection of the active layer of the threshold compensation transistor on the base substrate have a third overlapping region; and

40 a second part of capacitor of the channel capacitor of the threshold compensation transistor is located in the third overlapping region, and the second part of capacitor is formed by an overlapping portion between the auxiliary scan line and the active layer of the threshold compensation transistor.

In some examples, for the second scan line and the auxiliary scan line corresponding to the same sub-pixel, the orthographic projection of the second scan line on the base substrate overlaps the orthographic projection of the auxiliary scan line on the base substrate.

In some examples, the display panel further includes:

50 a third interlayer dielectric layer, located on a side, facing away from the base substrate, of the third conductive layer; and

55 a fourth conductive layer, located on a side, facing away from the base substrate, of the third interlayer dielectric layer and including a first connection part; where a first end of the first connection part is electrically connected with the compensation conductive part through a first via, and a second end of the first connection part is electrically connected with the gate of the drive transistor via a second via; and the first via penetrates the third interlayer dielectric layer, the second gate insulating layer and the second interlayer dielectric layer; and the second via penetrates the

60 third interlayer dielectric layer, the second gate insulating layer, the second interlayer dielectric layer, and the first interlayer dielectric layer.

In some examples, a third end of the first connection part is electrically connected with a conductor region of the active layer of the threshold compensation transistor through a third via; and the third via penetrates the second gate insulating layer and the third interlayer dielectric layer.

In some examples, for the first scan line and the third via corresponding to the same sub-pixel, the orthographic projection of the first scan line on the base substrate covers an orthographic projection of the third via on the base substrate.

In some examples, the first end and the third end of the first connection part extend substantially in the same direction, and the first end, the second end and the third end of the first connection part substantially form a T shape.

In some examples, for the same sub-pixel, the orthographic projection of the second scan line on the base substrate and an orthographic projection of the first connection part on the base substrate have a fourth overlapping region; an auxiliary capacitor is disposed in the fourth overlapping region, and the auxiliary capacitor is formed by an overlapping portion between the second scan line and the first connection part; and

a capacitance value of the auxiliary capacitor is substantially Δc_1 .

In some examples, the display panel further includes: an interlayer insulating layer, located on a side, facing away from the base substrate, of the fourth conductive layer; and

a fifth conductive layer, located on a side, facing away from the base substrate, of the interlayer insulating layer, and including a data line and a power line; where one column of sub-pixels corresponds to one data line and one power line; and

for the power line and the threshold compensation transistor corresponding to the same sub-pixel, an orthographic projection of the power line on the base substrate and the orthographic projection of the active layer of the threshold compensation transistor on the base substrate have an overlapping region.

In some examples, for the power line, the first via, the second via, the third via, and the third overlapping region corresponding to the same sub-pixel; the orthographic projection of the power line on the base substrate has overlapping regions with the first via, the second via, and the third via respectively; and the orthographic projection of the power line on the base substrate does not overlap the fourth overlapping region.

In some examples, the pixel circuit further includes a first reset transistor, and the oxide semiconductor layer further includes an active layer of the first reset transistor;

the third conductive layer further includes a first reset line, and one row of sub-pixels corresponds to one first reset line; and

for the first reset transistor and the first reset line corresponding to the same sub-pixel, an orthographic projection of the first reset line on the base substrate and an orthographic projection of the active layer of the first reset transistor on the base substrate have an overlapping region.

In some examples, for the power line and the first reset transistor corresponding to the same sub-pixel, the orthographic projection of the power line on the base substrate and the orthographic projection of the active layer of the first reset transistor on the base substrate have an overlapping region.

In some examples, for the first scan line, the second scan line, and the first reset line corresponding to the same sub-pixel, the orthographic projection of the first scan line

on the base substrate is located between the orthographic projections of the second scan line and the first reset line on the base substrate.

In some examples, the pixel circuit further includes a data writing transistor; and the display panel further includes:

a silicon semiconductor layer, located between the first conductive layer and the base substrate, and including an active layer of the data writing transistor; and

a first gate insulating layer, located between the first conductive layer and the silicon semiconductor layer; where

for the first scan line and the data writing transistor corresponding to the same sub-pixel, the orthographic projection of the first scan line on the base substrate and an orthographic projection of the active layer of the data writing transistor on the base substrate have an overlapping region.

In some examples, for the data writing transistor, the active layer of the threshold compensation transistor, and the compensation conductive part corresponding to the same sub-pixel: the orthographic projection of the compensation conductive part on the base substrate is located between the orthographic projection of the active layer of the data writing transistor on the base substrate and the orthographic

projection of the third via corresponding to the active layer of the threshold compensation transistor on the base substrate.

An embodiment of the present disclosure provides a display apparatus, including the display panel.

BRIEF DESCRIPTION OF THE DRAWINGS

DETAILED DESCRIPTION OF THE EMBODIMENTS

In order to make the objectives, technical solutions, and advantages of the embodiments of the present disclosure clearer, the technical solutions in embodiments of the present disclosure will be clearly and fully described in combination with the accompanying drawings of the embodiments of the present disclosure. It is apparent that the described embodiments are some, but not all, embodiments of the present disclosure. Also, embodiments and features in the embodiments of the disclosure may be combined with one another without conflict. Based on the described embodiments of the present disclosure, all other embodiments attainable by one of ordinary skilled in the art without involving any inventive effort are within the scope of the present disclosure.

Unless otherwise defined, the technical terms or scientific terms used in the present disclosure shall have the usual meanings understood by those with ordinary skills in the field to which the present disclosure belongs. "First", "second" and similar words used in the present disclosure do not indicate any order, quantity or importance, but are only used to distinguish different components. "Comprise" or "include" or other similar words mean that the element or item appearing before the word covers elements or items listed after the word and their equivalents, but does not exclude other elements or items. "Connecting" or "connected" or other similar words are not limited to physical or mechanical connections, but may include electrical connections, whether direct or indirect.

It should be noted that the dimensions and shapes of the various figures in the drawings are not to scale and are intended to be merely illustrative of the present disclosure. The same or similar reference numerals refer to the same or similar elements or elements having the same or similar functions throughout.

An embodiment of the present disclosure provides a pixel circuit, and as shown in FIG. 1, the pixel circuit may include:

a data writing transistor M3, where a gate of the data writing transistor M3 is electrically connected with a first scan line G1, a first electrode of the data writing transistor M3 is electrically connected with a data line DA, and a second electrode of the data writing transistor M3 is electrically connected with a first electrode of a drive transistor

M0; where a material of an active layer of the data writing transistor M3 is a low temperature poly-silicon material;

a threshold compensation transistor M2, where a gate of the threshold compensation transistor M2 is electrically connected with a second scan line G2, a first electrode of the threshold compensation transistor M2 is electrically connected with a gate of the drive transistor M0, and a second electrode of the threshold compensation transistor M2 is electrically connected with a second electrode of the drive transistor M0; where a material of an active layer of the threshold compensation transistor M2 is a metal oxide semiconductor material;

a compensation circuit 10, electrically connected with the gate of the drive transistor M0, and configured to compensate for a voltage of the gate of the drive transistor M0 according to a channel capacitor between the gate and the first electrode of the threshold compensation transistor M2; and

a light emitting control circuit 20, electrically connected with a first power end VDD, the first electrode and the second electrode of the drive transistor M0 and a first electrode of a light emitting device L, and configured to turn on the first power end VDD with the first electrode of the drive transistor M0 and turn on the second electrode of the drive transistor M0 with the first electrode of the light emitting device L under control of a signal of a light emitting control line EM to drive the light emitting device L to emit light.

In the above-mentioned pixel circuit provided by the embodiment of the present disclosure, the compensation circuit is electrically connected with the gate of the drive transistor, and the compensation circuit may compensate for the voltage of the gate of the drive transistor according to the channel capacitor between the gate and the first electrode of the threshold compensation transistor M2. Thus, when a level of a signal of the second scan line G2 is switched, a voltage $\Delta Vn1$, lowered by the channel capacitor between the gate and the first electrode of the threshold compensation transistor M2, of the voltage of the gate of the drive transistor M0 may be compensated through the compensation circuit, thereby improving the stability of the voltage of the gate of the drive transistor.

In specific implementation, in the embodiment of the present disclosure, the first electrode of the light emitting device L is electrically connected with the light emitting control circuit 20, and a second electrode of the light emitting device L is electrically connected with a second power end VSS. Exemplarily, the first electrode, electrically connected with the light emitting control circuit 20, of the light emitting device L is a positive electrode of the light emitting device L; and the second electrode, electrically connected with the second power end VSS, of the light emitting device L is a negative electrode of the light emitting device L. For example, the light emitting device L may be an electroluminescent diode, such as an OLED, a QLED, a Micro LED and a Mini LED. In addition, the light emitting device L realizes light emission under the action of a current when the drive transistor M0 is in a saturated state. In addition, generally, the light emitting device L has a turn-on voltage, and emits light when the voltage difference between two ends of the light emitting device L is greater than or equal to the turn-on voltage.

In specific implementation, in the embodiment of the present disclosure, a voltage Vdd of the first power end VDD is generally positive, and a voltage Vss of the second power end VSS is generally grounded or negative. In addition, a voltage Vinit of an initialization signal line VINIT and the

voltage V_{ss} of the second power end V_{SS} need to satisfy the formula: $V_{init} - V_{ss} < V_L$, where V_L is the turn-on voltage of the light emitting device L .

In specific implementation, in the embodiment of the present disclosure, as shown in FIG. 1, the drive transistor M_0 may be a P-type transistor, where the gate of the drive transistor M_0 may be its gate, the first electrode of the drive transistor M_0 may be its source, and the second electrode of the drive transistor M_0 may be its drain. Or, the drive transistor M_0 may also be an N-type transistor, where the gate of the drive transistor M_0 may be its gate, the first electrode of the drive transistor M_0 may be its drain, and the second electrode of the drive transistor M_0 may be its source. In actual applications, the type of the drive transistor M_0 may be specifically designed and determined according to actual application requirements, which is not limited here.

In specific implementation, in the embodiment of the present disclosure, as shown in FIG. 2, the compensation circuit **10** may include: a first compensation capacitor CF_1 , where a first electrode of the first compensation capacitor CF_1 is electrically connected with the gate of the drive transistor M_0 , and a second electrode of the first compensation capacitor CF_1 is electrically connected with the first scan line G_1 . Exemplarily, a capacitance value of the channel capacitor between the gate and the first electrode of the threshold compensation transistor M_2 is a first channel capacitance value C_{gsT2} , and a difference between a capacitance value C_1 of the first compensation capacitor CF_1 and the first channel capacitance value C_{gsT2} satisfies $0 \pm \Delta C_1$. For example, ΔC_1 may be 0.1, or ΔC_1 may also be 0.01, or ΔC_1 may also be 0.05, which is not limited here. It should be noted that in the actual process, due to the limitation of process conditions or other factors, the capacitance value of the first compensation capacitor CF_1 and the first channel capacitance value may not be exactly the same, and there may be some deviations. Therefore, the sameness relationship between the capacitance value of the first compensation capacitor CF_1 and the first channel capacitance value only needs to substantially satisfy the above-mentioned conditions, which all belong to the protection scope of the present disclosure. For example, when the difference between the capacitance value of the first compensation capacitor CF_1 and the first channel capacitance value satisfies $0 \pm \Delta C_1$, it may be considered that the capacitance value of the first compensation capacitor CF_1 and the first channel capacitance value are allowed to be the same within the tolerable error range.

In specific implementation, in the embodiment of the present disclosure, as shown in FIG. 2, the pixel circuit may further include: a first reset transistor M_1 ; a gate of the first reset transistor M_1 is electrically connected with a first reset line S_1 , a first electrode of the first reset transistor M_1 is electrically connected with the initialization signal line V_{INIT} , and a second electrode of the first reset transistor M_1 is electrically connected with the gate of the drive transistor M_0 .

In specific implementation, in the embodiment of the present disclosure, as shown in FIG. 1, the pixel circuit further includes: a second reset transistor M_4 , where a gate of the second reset transistor M_4 is electrically connected with a second reset line S_2 , a first electrode of the second reset transistor M_4 is electrically connected with the initialization signal line V_{INIT} , and a second electrode of the second reset transistor M_4 is electrically connected with the first electrode of the light emitting device L . Exemplarily, the second reset line S_2 may be the same signal end as the first scan line G_1 . For example, as shown in FIG. 2, the gate

of the data writing transistor M_3 and the gate of the second reset transistor M_4 are both electrically connected with the first scan line G_1 .

In specific implementation, in the embodiment of the present disclosure, as shown in FIG. 2, a pixel circuit may include: a first light emitting control transistor M_5 , a second light emitting control transistor M_6 and a storage capacitor C_1 . A gate of the first light emitting control transistor M_5 is electrically connected with the light emitting control line EM , a first electrode of the first light emitting control transistor M_5 is electrically connected with the first power end V_{DD} , and a second electrode of the first light emitting control transistor M_5 is electrically connected with the first electrode of the drive transistor M_0 . A gate of the second light emitting control transistor M_6 is electrically connected with the light emitting control line EM , a first electrode of the second light emitting control transistor M_6 is electrically connected with the second electrode of the drive transistor M_0 , and a second electrode of the second light emitting control transistor M_6 is electrically connected with the first electrode of the light emitting device L . A first electrode of the storage capacitor C_1 is electrically connected with the first power end V_{DD} , and a second electrode of the storage capacitor C_1 is electrically connected with the gate of the drive transistor M_0 .

Exemplarily, as shown in FIG. 2, the data writing transistor M_3 , the second reset transistor M_4 , the first light emitting control transistor M_5 , the second light emitting control transistor M_6 , and the drive transistor M_0 may all be set as P-type transistors. Of course, the data writing transistor M_3 , the second reset transistor M_4 , the first light emitting control transistor M_5 , the second light emitting control transistor M_6 , and the drive transistor M_0 may all be set as N-type transistors. Of course, in actual applications, the specific types of the data writing transistor M_3 , the second reset transistor M_4 , the first light emitting control transistor M_5 , the second light emitting control transistor M_6 , and the drive transistor M_0 may be determined according to actual application requirements, which is not limited here.

Exemplarily, as shown in FIG. 2, both the first reset transistor M_1 and the threshold compensation transistor M_2 may be set as N-type transistors. Of course, both the first reset transistor M_1 and the threshold compensation transistor M_2 may be set as P-type transistors. Of course, in actual applications, the specific types of the first reset transistor M_1 and the threshold compensation transistor M_2 may be determined according to actual application requirements, which is not limited here.

Exemplarily, in the embodiment of the present disclosure, the P-type transistor is turned on under the action of a low-level signal, and is turned off under the action of a high-level signal; and the N-type transistor is turned on under the action of a high-level signal, and is turned off under the action of a low-level signal.

Exemplarily, in the embodiment of the present disclosure, gates of the above-mentioned transistors may be used as their gates, first electrodes of the transistors may be used as their sources, and second electrodes of the transistors may be used as their drains; or the first electrodes of the above-mentioned transistors may be used as their drains, and the second electrodes of the above-mentioned transistors may be used as their sources, which is not specifically distinguished here.

Generally, transistors that use low temperature poly-silicon (LTPS) materials as active layers have high mobility, may be made thinner and smaller, and have lower power

11

consumption. In specific implementation, in the embodiment of the present disclosure, a material of an active layer of the drive transistor **M0** may include an LTPS material, the material of the active layer of the data writing transistor **M3** may include the LTPS material, a material of the second reset transistor **M4** may include the LTPS material, a material of the first light emitting control transistor **M5** may include the LTPS material, and a material of the second light emitting control transistor **M6** may include the LTPS material. That is, the data writing transistor **M3**, the second reset transistor **M4**, the first light emitting control transistor **M5**, the second light emitting control transistor **M6**, and the drive transistor **M0** are all set as LTPS type transistors, so that the data writing transistor **M3**, the second reset transistor **M4**, the first light emitting control transistor **M5**, the second light emitting control transistor **M6**, and the drive transistor **M0** have higher mobility, may be made thinner and smaller, and have lower power consumption.

Generally, leakage currents of transistors that use metal oxide semiconductor materials as active layers are relatively small. Therefore, in order to reduce leakage currents, in specific implementation, in the embodiment of the present disclosure, a material of an active layer of the first reset transistor **M1** may include a metal oxide semiconductor material, and the material of the active layer of the threshold compensation transistor **M2** may include the metal oxide semiconductor material. That is, both the first reset transistor **M1** and the threshold compensation transistor **M2** are set as oxide type transistors, so that the leakage currents of the first reset transistor **M1** and the threshold compensation transistor **M2** may be relatively small. Exemplarily, the metal oxide semiconductor material may be indium gallium zinc oxide (IGZO). Of course, the metal oxide semiconductor material may also be other metal oxide semiconductor materials, which is not limited here. Thus, the leakage currents of the first reset transistor **M1** and the threshold compensation transistor **M2** when the first reset transistor **M1** and the threshold compensation transistor **M2** are turned off may be reduced; and when the light emitting device **L** emits light, the interference of the leakage currents on the voltage of the gate of the drive transistor **M0** may be reduced, thereby improving the stability of a drive current for the drive transistor **M0** to drive the light emitting device **L** to emit light.

In the pixel circuit provided by the embodiment of the present disclosure, processes for preparing the LTPS type transistors and the oxide type transistors are combined to prepare the pixel circuit with low temperature poly-silicon combined with oxides, so that a leakage current of the gate of the drive transistor **M0** is relatively small, and the power consumption is relatively low. Therefore, when the pixel circuit is applied to a display apparatus with an electroluminescent display panel, the stability of the voltage of the gate of the drive transistor **M0** may be improved, and especially when the display apparatus reduces the refresh rate for display, the uniformity of display may be ensured.

The operation of the pixel circuit provided by the embodiment of the present disclosure will now be described with reference to a signal timing diagram shown in FIG. 3, taking the structure shown in FIG. 2 as an example. In the following description, a high level is denoted by 1, and a low level is denoted by 0. It should be noted that 1 and 0 are logic levels only to better explain the specific operation of the embodiment of the present disclosure, and not specific voltage values.

It should be noted that a signal of the first scan line **G1** and a signal of the second scan line **G2** are composed of a

12

high-level signal and a low-level signal, respectively. A voltage of the high-level signal is typically a high voltage **VGH** and a voltage of the low-level signal is typically a low voltage **VGL**. Of course, specific values of the high voltage **VGH** and the low voltage **VGL** may be designed and determined according to actual application requirements, which is not limited here.

Exemplarily, the absolute values of high and low levels may be equal, for example, the high level is +5 V, and the low level is -5 V. Or, the high level is +6 V, and the low level is -6 V. Or, the high level is +7 V, and the low level is -7 V. Or, the absolute values of the high and low levels may also be unequal, for example, the high level is a value greater than 0, and the low level is 0 V. Of course, in actual applications, the relationship between the absolute values of the high and low levels may be determined according to the actual application requirements, which is not limited here.

In a reset stage **T1**, **S1=1**, **G2=0**, **G1=1**, **EM=1**.

Since **S1=1**, the first reset transistor **M1** is turned on to provide a signal of the initialization signal line **VINIT** to the gate of the drive transistor **M0** to initialize the gate of the drive transistor **M0**. Since **G2=0**, the threshold compensation transistor **M2** is turned off. Since **G1=1**, both the data writing transistor **M3** and the second reset transistor **M4** are turned off. Since **EM=1**, both the first light emitting control transistor **M5** and the second light emitting control transistor **M6** are turned off. A voltage of the second electrode of the first compensation capacitor **CF1** is the high voltage **VGH** of the high-level signal of the first scan line **G1**, and a voltage of the first electrode of the first compensation capacitor **CF1** is the voltage **Vinit** of the initialization signal line **VINIT**.

In a data writing stage **T2**, **S1=0**, **G2=1**, **G1=0**, and **EM=1**.

Since **G1=0**, the data writing transistor **M3** and the second reset transistor **M4** are both turned on. Since **G2=1**, the threshold compensation transistor **M2** is turned on. The turned-on data writing transistor **M3** inputs a data voltage **Vda** of the data line **DA** to the first electrode of the drive transistor **M0**. The turned-on threshold compensation transistor **M2** turns on the gate and the second electrode of the drive transistor **M0**, so that the drive transistor **M0** forms a diode electrical connection structure, the gate of the drive transistor **M0** is charged through the data voltage **Vda**, and the voltage of the gate of the drive transistor **M0** is made to successfully be **Vda+Vth**. The turned-on second reset transistor **M4** provides the signal of the initialization signal line **VINIT** to the first electrode of the light emitting device **L**, to initialize the first electrode of the light emitting device **L**. The voltage of the second electrode of the first compensation capacitor **CF1** is the low voltage **VGL** of the low-level signal of the first scan line **G1**, and the voltage of the first electrode of the first compensation capacitor **CF1** is **Vda+Vth**. Since **S1=0**, the first reset transistor **M1** is turned off. Since **EM=1**, both the first light emitting control transistor **M5** and the second light emitting control transistor **M6** are turned off.

In a light emitting stage **T3**, **S1=0**, **G2=0**, **G1=1**, and **EM=0**.

Since the second scan line **G2** is switched from the high voltage **VGH** of the high-level signal to the low voltage **VGL** of the low-level signal, the voltage of the gate of the drive transistor **M0** may be changed by a voltage **ΔVn11** on the basis of **Vda+Vth**.

$$\Delta Vn11 = \frac{CgsT2}{CgsT2 + Cc1 + Cf1 + Co} * (VGL - VGH);$$

where C_{gsT2} represents the first channel capacitance value, C_{c1} represents a capacitance value of the storage capacitor $C1$, C_{f1} represents the capacitance value of the first compensation capacitor $CF1$, and C_o represents other related capacitance values (generally being fixed values).

Since the first scan line $G1$ is switched from the low voltage VGL of the low-level signal to the high voltage VGH of the high-level signal, the voltage of the gate of the drive transistor $M0$ may be changed by a voltage $\Delta Vn12$ on the basis of $Vda+Vth$; where

$$\Delta Vn12 = \frac{C_{f1}}{C_{gsT2} + C_{c1} + C_{f1} + C_o} * (VGL - VGH).$$

Thus, the amount of change in the voltage of the gate of the drive transistor $M0$ is: $\Delta Vn10 = \Delta Vn11 + \Delta Vn12$. Since the difference between the capacitance value C_{f1} of the first compensation capacitor $CF1$ and the first channel capacitance value C_{gsT2} satisfies $0 \pm \Delta c1$, it may be considered that the capacitance value C_{f1} of the first compensation capacitor $CF1$ and the first channel capacitance value C_{gsT2} are equal. Therefore, $\Delta Vn11$ and $\Delta Vn12$ may cancel each other out, and $\Delta Vn10$ may be 0. In this way, after the light emitting stage $T3$, the voltage of the gate of the drive transistor $M0$ may be stabilized at $Vda+Vth$.

Since $EM=0$, the first light emitting control transistor $M5$ and the second light emitting control transistor $M6$ are both turned on. The turned-on first light emitting control transistor $M5$ provides a voltage of the first power end VDD to the first electrode of the drive transistor $M0$. The drive transistor $M0$ generates an operating current Ids under the action of voltages of the gate and first electrode of the drive transistor $M0$. $Ids = K(Vdd - Vda)^2$, where K is a structural parameter. The turned-on second light emitting control transistor $M6$ turns on the second electrode of the drive transistor $M0$ and the first electrode of the light emitting device L , so that the light emitting device L is driven through the operating current Ids to emit light. Therefore, an operating current generated by the pixel circuit provided by the embodiment of the present disclosure has nothing to do with the threshold voltage Vth of the drive transistor $M0$.

The embodiment of the present disclosure further provides some pixel circuits. The schematic structural diagram of the pixel circuits is shown in FIG. 4, which is modified in accordance with the implementation in the above-mentioned embodiment. The following only describes the differences between the present embodiment and the above-mentioned embodiment, and the similarities are not repeated here.

In specific implementation, in the embodiment of the present disclosure, as shown in FIG. 4, the compensation circuit **10** may include: a first compensation control transistor, where a gate of the first compensation control transistor is electrically connected with the first scan line $G1$, and both a first electrode and a second electrode of the first compensation control transistor are electrically connected with the gate of the drive transistor $M0$. Exemplarily, the first compensation control transistor may be a P-type transistor. Further, a material of an active layer of the first compensation control transistor may be a low temperature poly-silicon material or a metal oxide semiconductor material, which is not limited here.

In specific implementation, in the embodiment of the present disclosure, a capacitance value of a channel capacitor between the gate and the first electrode of the first compensation control transistor is a second channel capaci-

tance value C_{gsMF1} , and a capacitance value of a channel capacitor between the gate and the second electrode of the first compensation control transistor is a third channel capacitance value C_{gdMF1} ; and the sum of the second channel capacitance value C_{gsMF1} and the third channel capacitance value C_{gdMF1} is a total channel capacitance value C_{mMF1} . A difference between the total channel capacitance value C_{mMF1} and the first channel capacitance value C_{gsT2} satisfies $0 \pm \Delta c2$. For example, $\Delta c2$ may be 0.1, 0.01, or 0.05, which is not limited here. It should be noted that in the actual process, due to the limitation of process conditions or other factors, the first channel capacitance value may not be exactly the same as the total channel capacitance value, and there may be some deviations. Therefore, the sameness relationship between the first channel capacitance value and the total channel capacitance value only needs to substantially satisfy the above-mentioned conditions, which all belong to the protection scope of the present disclosure. For example, when the difference between the first channel capacitance value and the total channel capacitance value satisfies $0 \pm \Delta c2$, it may be considered that the first channel capacitance value and the total channel capacitance value are allowed to be the same within the tolerable error range.

The operation of the pixel circuit provided by the embodiment of the present disclosure will now be described with reference to the signal timing diagram shown in FIG. 3, taking the structure shown in FIG. 4 as an example. In the following description, the high level is denoted by 1, and the low level is denoted by 0. It should be noted that 1 and 0 are logic levels only to better explain the specific operation of the embodiment of the present disclosure, and not specific voltage values.

It should be noted that the signal of the first scan line $G1$ and the signal of the second scan line $G2$ are composed of the high-level signal and the low-level signal, respectively. The voltage of the high-level signal is typically the high voltage VGH and the voltage of the low-level signal is typically the low voltage VGL . Of course, the specific values of the high voltage VGH and the low voltage VGL may be designed and determined according to actual application requirements, which is not limited here.

In the reset stage $T1$, $S1=1$, $G2=0$, $G1=1$, and $EM=1$.

Since $S1=1$, the first reset transistor $M1$ is turned on to provide the signal of the initialization signal line $VINIT$ to the gate of the drive transistor $M0$ to initialize the gate of the drive transistor $M0$. Since $G2=0$, the threshold compensation transistor $M2$ is turned off. Since $G1=1$, the data writing transistor $M3$, the first compensation control transistor and the second reset transistor $M4$ are all turned off. Since $EM=1$, both the first light emitting control transistor $M5$ and the second light emitting control transistor $M6$ are turned off.

In the data writing stage $T2$, $S1=0$, $G2=1$, $G1=0$, and $EM=1$.

Since $G1=0$, the data writing transistor $M3$, the second reset transistor $M4$ and the first compensation control transistor are all turned on. Since $G2=1$, the threshold compensation transistor $M2$ is turned on. The turned-on data writing transistor $M3$ inputs the data voltage Vda of the data line DA to the first electrode of the drive transistor $M0$. The turned-on threshold compensation transistor $M2$ turns on the gate and the second electrode of the drive transistor $M0$, so that the drive transistor $M0$ forms a diode electrical connection structure, the gate of the drive transistor $M0$ is charged through the data voltage Vda , and the voltage of the gate of the drive transistor $M0$ is made to successfully be $Vda+Vth$.

15

The turned-on second reset transistor **M4** provides the signal of the initialization signal line **VINIT** to the first electrode of the light emitting device **L** to initialize the first electrode of the light emitting device **L**. Since **S1**=0, the first reset transistor **M1** is turned off. Since **EM**=1, both the first light emitting control transistor **M5** and the second light emitting control transistor **M6** are turned off. In this stage, the first compensation control transistor has no influence on the voltage of the gate of the drive transistor **M0**.

In the light emitting stage **T3**, **S1**=0, **G2**=0, **G1**=1, and **EM**=0.

Since the second scan line **G2** is switched from the high voltage **VGH** of the high-level signal to the low voltage **VGL** of the low-level signal, the voltage of the gate of the drive transistor **M0** may be changed by a voltage $\Delta Vn21$ on the basis of $Vda+Vth$.

$$\Delta Vn21 = \frac{CgsT2}{CgsT2 + Cc1 + CgsMF1 + CgdMF1 + Co} * (VGL - VGH),$$

where **CgsT2** represents the first channel capacitance value, **Cc1** represents the capacitance value of the storage capacitor **C1**, **CgsMF1** represents the second channel capacitance value, **CgdMF1** represents the third channel capacitance value, and **Co** represents other related capacitance values (generally being fixed values).

Since the first scan line **G1** is switched from the low voltage **VGL** of the low-level signal to the high voltage **VGH** of the high-level signal, the voltage of the gate of the drive transistor **M0** may be changed by a voltage $\Delta Vn22$ on the basis of $Vda+Vth$, where

$$\Delta Vn22 = \frac{CgsMF1 + CgdMF1}{CgsT2 + Cc1 + CgsMF1 + Co} * (VGL - VGH).$$

Thus, the amount of change in the voltage of the gate of the drive transistor **M0** is: $\Delta Vn20=\Delta Vn21+\Delta Vn22$. Since the difference between the total channel capacitance value **CmMF1**, namely the sum of the second channel capacitance value **CgsMF1** and the third channel capacitance value **CgdMF1**, and the first channel capacitance value **CgsT2** satisfies $0\pm\Delta c2$, it may be considered that the total channel capacitance value **CmMF1** and the first channel capacitance value **CgsT2** are equal. Therefore, $\Delta Vn21$ and $\Delta Vn22$ may cancel each other out, and $\Delta Vn20$ may be 0. In this way, after the light emitting stage **T3**, the voltage of the gate of the drive transistor **M0** may be stabilized at $Vda+Vth$.

Since **EM**=0, the first light emitting control transistor **M5** and the second light emitting control transistor **M6** are both turned on. The turned-on first light emitting control transistor **M5** provides the voltage of the first power end **VDD** to the first electrode of the drive transistor **M0**. The drive transistor **M0** generates the operating current **Ids** under the action of the voltages of the gate and first electrode of the drive transistor **M0**. $Ids=K(Vdd-Vda)^2$, where **K** is a structural parameter. The turned-on second light emitting control transistor **M6** turns on the second electrode of the drive transistor **M0** and the first electrode of the light emitting device **L**, so that the light emitting device **L** is driven through the operating current **Ids** to emit light. Therefore, the operating current generated by the pixel circuit provided by the embodiment of the present disclosure has nothing to do with the threshold voltage **Vth** of the drive transistor **M0**.

16

The embodiment of the present disclosure further provides some pixel circuits. The schematic structural diagram of the pixel circuits is shown in FIG. 5, which is modified in accordance with the implementation in the above-mentioned embodiment. The following only describes the differences between the present embodiment and the above-mentioned embodiment, and the similarities are not repeated here.

In specific implementation, in the embodiment of the present disclosure, as shown in FIG. 5, the compensation circuit **10** may further include: a second compensation control transistor, where a gate of the second compensation control transistor is electrically connected with the first scan line **G1**, a first electrode of the second compensation control transistor is electrically connected with the gate of the drive transistor **M0**, and a second electrode of the second compensation control transistor is in suspended connection. Exemplarily, the second compensation control transistor may be a P-type transistor. Further, a material of an active layer of the second compensation control transistor may be a low temperature poly-silicon material or a metal oxide semiconductor material, which is not limited here.

In specific implementation, in the embodiment of the present disclosure, a capacitance value of a channel capacitor between the gate and the first electrode of the second compensation control transistor is a fourth channel capacitance value **CgsMF2**, and a difference between the fourth channel capacitance value **CgsMF2** and the first channel capacitance value **CgsT2** satisfies $0\pm\Delta c3$. For example, $\Delta c3$ may be 0.1, or 0.01, or 0.05, which is not limited here. It should be noted that in the actual process, due to the limitation of process conditions or other factors, the first channel capacitance value may not be exactly the same as the fourth channel capacitance value, and there may be some deviations. Therefore, the sameness relationship between the first channel capacitance value and the fourth channel capacitance value only needs to substantially satisfy the above-mentioned conditions, which all belong to the protection scope of the present disclosure. For example, when the difference between the first channel capacitance value and the fourth channel capacitance value satisfies $0\pm\Delta c3$, it may be considered that the first channel capacitance value and the fourth channel capacitance value are allowed to be the same within the tolerable error range.

The operation of the pixel circuit provided by the embodiment of the present disclosure will now be described with reference to the signal timing diagram shown in FIG. 3, taking the structure shown in FIG. 5 as an example. In the following description, the high level is denoted by 1, and the low level is denoted by 0. It should be noted that 1 and 0 are logic levels only to better explain the specific operation of the embodiment of the present disclosure, and not specific voltage values.

It should be noted that the signal of the first scan line **G1** and the signal of the second scan line **G2** are composed of the high-level signal and the low-level signal, respectively. The voltage of the high-level signal is typically the high voltage **VGH** and the voltage of the low-level signal is typically the low voltage **VGL**. Of course, the specific values of the high voltage **VGH** and the low voltage **VGL** may be designed and determined according to actual application requirements, which is not limited here.

In the reset stage **T1**, **S1**=1, **G2**=0, **G1**=1, and **EM**=1.

Since **S1**=1, the first reset transistor **M1** is turned on to provide the signal of the initialization signal line **VINIT** to the gate of the drive transistor **M0** to initialize the gate of the drive transistor **M0**. Since **G2**=0, the threshold compensation transistor **M2** is turned off. Since **G1**=1, the data writing

transistor **M3**, the second compensation control transistor and the second reset transistor **M4** are all turned off. Since $EM=1$, both the first light emitting control transistor **M5** and the second light emitting control transistor **M6** are turned off.

In the data writing stage **T2**, $S1=0$, $G2=1$, $G1=0$, and $EM=1$.

Since $G1=0$, the data writing transistor **M3**, the second reset transistor **M4** and the second compensation control transistor are all turned on. Since $G2=1$, the threshold compensation transistor **M2** is turned on. The turned-on data writing transistor **M3** inputs the data voltage Vda of the data line **DA** to the first electrode of the drive transistor **M0**. The turned-on threshold compensation transistor **M2** turns on the gate and the second electrode of the drive transistor **M0**, so that the drive transistor **M0** forms a diode electrical connection structure, the gate of the drive transistor **M0** is charged through the data voltage Vda , and the voltage of the gate of the drive transistor **M0** is made to successfully be $Vda+Vth$. The turned-on second reset transistor **M4** provides the signal of the initialization signal line **VINIT** to the first electrode of the light emitting device **L** to initialize the first electrode of the light emitting device **L**. Since $S1=0$, the first reset transistor **M1** is turned off. Since $EM=1$, both the first light emitting control transistor **M5** and the second light emitting control transistor **M6** are turned off. In this stage, the second compensation control transistor has no influence on the voltage of the gate of the drive transistor **M0**.

In the light emitting stage **T3**, $S1=0$, $G2=0$, $G1=1$, and $EM=0$.

Since the second scan line **G2** is switched from the high voltage **VGH** of the high-level signal to the low voltage **VGL** of the low-level signal, the voltage of the gate of the drive transistor **M0** may be changed by a voltage $\Delta Vn31$ on the basis of $Vda+Vth$.

$$\Delta Vn31 = \frac{CgsT2}{CgsT2 + Cc1 + CgsMF2 + Co} * (VGL - VGH),$$

where $CgsT2$ represents the first channel capacitance value, $Cc1$ represents the capacitance value of the storage capacitor **C1**, $CgsMF2$ represents the fourth channel capacitance value, and Co represents other related capacitance values (generally being fixed values).

Since the first scan line **G1** is switched from the low voltage **VGL** of the low-level signal to the high voltage **VGH** of the high-level signal, the voltage of the gate of the drive transistor **M0** may be changed by a voltage $\Delta Vn32$ on the basis of $Vda+Vth$.

$$\Delta Vn32 = \frac{CgsMF2}{CgsT2 + Cc1 + CgsMF2 + Co} * (VGL - VGH).$$

Thus, the amount of change in the voltage of the gate of the drive transistor **M0** is: $\Delta Vn30 = \Delta Vn31 + \Delta Vn32$. Since the difference between the fourth channel capacitance value $CgsMF2$ and the first channel capacitance value $CgsT2$ satisfies $0 \pm \Delta C$, it may be considered that the fourth channel capacitance value $CgsMF2$ and the first channel capacitance value $CgsT2$ are equal. Therefore, $\Delta Vn31$ and $\Delta Vn32$ may cancel each other out, and $\Delta Vn30$ may be 0. In this way, after the light emitting stage **T3**, the voltage of the gate of the drive transistor **M0** may be stabilized at $Vda+Vth$.

Since $EM=0$, the first light emitting control transistor **M5** and the second light emitting control transistor **M6** are both turned on. The turned-on first light emitting control transistor **M5** provides the voltage of the first power end **VDD** to the first electrode of the drive transistor **M0**. The drive transistor **M0** generates the operating current Ids under the action of the voltages of the gate and first electrode of the drive transistor **M0**. $Ids = K(Vdd - Vda)^2$, where K is a structural parameter. The turned-on second light emitting control transistor **M6** turns on the second electrode of the drive transistor **M0** and the first electrode of the light emitting device **L**, so that the light emitting device **L** is driven through the operating current Ids to emit light. Therefore, the operating current generated by the pixel circuit provided by the embodiment of the present disclosure has nothing to do with the threshold voltage Vth of the drive transistor **M0**.

The embodiment of the present disclosure further provides some pixel circuits. The schematic structural diagram of the pixel circuits is shown in FIG. 6, which is modified in accordance with the implementation in the above-mentioned embodiment. The following only describes the differences between the present embodiment and the above-mentioned embodiment, and the similarities are not repeated here.

In specific implementation, in the embodiment of the present disclosure, as shown in FIG. 6, the compensation circuit **10** may further include: a second compensation capacitor **CF2**. A first electrode of the second compensation capacitor **CF2** is electrically connected with the gate of the drive transistor **M0**, and a second electrode of the second compensation capacitor **CF2** is electrically connected with the first electrode of the light emitting device **L**. Exemplarily, a capacitance value $Cf2$ of the second compensation capacitor **CF2** is related to the first channel capacitance value $CgsT2$.

The operation of the pixel circuit provided by the embodiment of the present disclosure will now be described with reference to the signal timing diagram shown in FIG. 3, taking the structure shown in FIG. 6 as an example. In the following description, the high level is denoted by 1, and the low level is denoted by 0. It should be noted that 1 and 0 are logic levels only to better explain the specific operation of the embodiment of the present disclosure, and not specific voltage values.

In the reset stage **T1**, $S1=1$, $G2=0$, $G1=1$, and $EM=1$. Since $S1=1$, the first reset transistor **M1** is turned on to provide the signal of the initialization signal line **VINIT** to the gate of the drive transistor **M0** to initialize the gate of the drive transistor **M0**. Since $G2=0$, the threshold compensation transistor **M2** is turned off. Since $G1=1$, the data writing transistor **M3** and the second reset transistor **M4** are all turned off. Since $EM=1$, both the first light emitting control transistor **M5** and the second light emitting control transistor **M6** are turned off. A voltage of the first electrode of the second compensation capacitor **CF2** is the voltage **Vinit** of the initialization signal line **VINIT**, and a voltage of the second electrode of the second compensation capacitor **CF2** is the voltage of the first electrode of the light emitting device **L**.

In the data writing stage **T2**, $S1=0$, $G2=1$, $G1=0$, and $EM=1$.

Since $G1=0$, the data writing transistor **M3** and the second reset transistor **M4** are both turned on. Since $G2=1$, the threshold compensation transistor **M2** is turned on. The turned-on data writing transistor **M3** inputs the data voltage Vda of the data line **DA** to the first electrode of the drive transistor **M0**. The turned-on threshold compensation transistor **M2** turns on the gate and the second electrode of the

drive transistor **M0**, so that the drive transistor **M0** forms a diode electrical connection structure, the gate of the drive transistor **M0** is charged through the data voltage V_{da} , and the voltage of the gate of the drive transistor **M0** is made to successfully be $V_{da}+V_{th}$. The turned-on second reset transistor **M4** provides the signal of the initialization signal line V_{INIT} to the first electrode of the light emitting device **L** to initialize the first electrode of the light emitting device **L**. The voltage of the first electrode of the second compensation capacitor **CF2** is $V_{da}+V_{th}$, and the voltage of the second electrode of the second compensation capacitor **CF2** is the voltage V_{init} of the initialization signal line V_{INIT} . Since $S1=0$, the first reset transistor **M1** is turned off. Since $EM=1$, both the first light emitting control transistor **M5** and the second light emitting control transistor **M6** are turned off.

In the light emitting stage **T3**, $S1=0$, $G2=0$, $G1=1$, and $EM=0$.

Since the second scan line **G2** is switched from the high voltage V_{GH} of the high-level signal to the low voltage V_{GL} of the low-level signal, the voltage of the gate of the drive transistor **M0** may be changed by a voltage ΔV_{n41} on the basis of $V_{da}+V_{th}$.

$$\Delta V_{n41} = \frac{C_{gsT2}}{C_{gsT2} + C_{c1} + C_{f2} + C_o} * (V_{GL} - V_{GH}),$$

where C_{gsT2} represents the first channel capacitance value, C_{c1} represents the capacitance value of the storage capacitor **C1**, C_{f2} represents the capacitance value of the second compensation capacitor **CF2**, and C_o represents other related capacitance values (generally being fixed values).

Since the voltage of the first electrode of the light emitting device **L** is changed from V_{init} to $V_{ss}+V_{L}$, the voltage of the gate of the drive transistor **M0** may be changed by a voltage ΔV_{n42} on the basis of $V_{da}+V_{th}$.

$$\Delta V_{n42} = \frac{C_{f2}}{C_{gsT2} + C_{c1} + C_{f2} + C_o} * (V_{L} + V_{ss} - V_{init}).$$

Thus, the amount of change in the voltage of the gate of the drive transistor **M0** is: $\Delta V_{n40}=\Delta V_{n41}+\Delta V_{n42}$. By enabling $C_{gsT2}*(V_{GL}-V_{GH})+C_{f2}*(V_{L}+V_{ss}-V_{init})$ to be substantially 0, ΔV_{n41} and ΔV_{n42} may cancel each other out, and ΔV_{n40} may be 0. In this way, after the light emitting stage **T3**, the voltage of the gate of the drive transistor **M0** may be stabilized at $V_{da}+V_{th}$.

Since $EM=0$, the first light emitting control transistor **M5** and the second light emitting control transistor **M6** are both turned on. The turned-on first light emitting control transistor **M5** provides the voltage of the first power end VDD to the first electrode of the drive transistor **M0**. The drive transistor **M0** generates the operating current Ids under the action of the voltages of the gate and first electrode of the drive transistor **M0**. $Ids=K(V_{dd}-V_{da})^2$, where K is a structural parameter. The turned-on second light emitting control transistor **M6** turns on the second electrode of the drive transistor **M0** and the first electrode of the light emitting device **L**, so that the light emitting device **L** is driven through the operating current Ids to emit light. Therefore, the operating current generated by the pixel circuit provided by the embodiment of the present disclosure has nothing to do with the threshold voltage V_{th} of the drive transistor **M0**.

The embodiment of the present disclosure further provides some pixel circuits. The schematic structural diagram

of the pixel circuits is shown in FIG. 7A, which is modified in accordance with the implementation in the above-mentioned embodiment. The following only describes the differences between the present embodiment and the above-mentioned embodiment, and the similarities are not repeated here.

In specific implementation, in the embodiment of the present disclosure, as shown in FIG. 7A, the pixel circuit may further include: a stable transistor **M7**. A gate of the stable transistor **M7** is electrically connected with a stable control signal end VS , a first electrode of the stable transistor **M7** is electrically connected with the gate of the drive transistor **M0**, and a second electrode of the stable transistor **M7** is electrically connected with the second electrode of the first reset transistor **M1** and the first electrode of the threshold compensation transistor **M2**. That is, the second electrode of the first reset transistor **M1** and the first electrode of the threshold compensation transistor **M2** are electrically with the gate of the drive transistor **M0** through the stable transistor **M7**.

Exemplarily, the first reset transistor **M1** and the threshold compensation transistor **M2** may be P-type transistors, and the materials of the active layers of the first reset transistor **M1** and the threshold compensation transistor **M2** are LTPS materials.

Exemplarily, the stable transistor **M7** may be an N-type transistor, and a material of an active layer of the stable transistor **M7** may be a metal oxide semiconductor material.

The operation of the pixel circuit provided by the embodiment of the present disclosure will now be described with reference to a signal timing diagram shown in FIG. 7B, taking the structure shown in FIG. 7A as an example. In the following description, the high level is denoted by 1, and the low level is denoted by 0. It should be noted that 1 and 0 are logic levels only to better explain the specific operation of the embodiment of the present disclosure, and not specific voltage values.

In the reset stage **T1**, $S1=0$, $G2=1$, $G1=1$, $EM=1$, and $VS=1$.

Since $S1=0$, the first reset transistor **M1** is turned on to provide the signal of the initialization signal line V_{INIT} to the second electrode of the stable transistor **M7**. Since $VS=1$, the stable transistor **M7** is turned on to provide the signal of the initialization signal line V_{INIT} to the gate of the drive transistor **M0** so as to initialize the gate of the drive transistor **M0**. Since $G2=1$, the threshold compensation transistor **M2** is turned off. Since $G1=1$, the data writing transistor **M3** and the second reset transistor **M4** are both turned off. Since $EM=1$, both the first light emitting control transistor **M5** and the second light emitting control transistor **M6** are turned off. The voltage of the second electrode of the first compensation capacitor **CF1** is the high voltage V_{GH} of the high-level signal of the first scan line **G1**, and the voltage of the first electrode of the first compensation capacitor **CF1** is the voltage V_{init} of the initialization signal line V_{INIT} .

In the data writing stage **T2**, $S1=1$, $G2=0$, $G1=0$, $EM=1$, and $VS=1$.

Since $G1=0$, the data writing transistor **M3** and the second reset transistor **M4** are both turned on. Since $G2=0$, the threshold compensation transistor **M2** is turned on. Since $VS=1$, the stable transistor **M7** is turned on. The turned-on data writing transistor **M3** inputs the data voltage V_{da} of the data line **DA** to the first electrode of the drive transistor **M0**. The turned-on threshold compensation transistor **M2** and the turned-on stable transistor **M7** turn on the gate and the second electrode of the drive transistor **M0**, so that the drive transistor **M0** forms a diode electrical connection structure,

the gate of the drive transistor **M0** is charged through the data voltage V_{da} , and the voltage of the gate of the drive transistor **M0** is made to successfully be $V_{da}+V_{th}$. The turned-on second reset transistor **M4** provides the signal of the initialization signal line **VINIT** to the first electrode of the light emitting device **L** to initialize the first electrode of the light emitting device **L**. The voltage of the second electrode of the first compensation capacitor **CF1** is the low voltage V_{GL} of the low-level signal of the first scan line **G1**, and the voltage of the first electrode of the first compensation capacitor **CF1** is $V_{da}+V_{th}$. Since **S1**=1, the first reset transistor **M1** is turned off. Since **EM**=1, both the first light emitting control transistor **M5** and the second light emitting control transistor **M6** are turned off.

In the light emitting stage **T3**, **S1**=0, **G2**=0, **G1**=1, **EM**=0, and **VS**=0.

Since the second scan line **G2** is switched from the high voltage V_{GH} of the high-level signal to the low voltage V_{GL} of the low-level signal, the voltage of the gate of the drive transistor **M0** may be changed by a voltage ΔV_{n11} on the basis of $V_{da}+V_{th}$.

$$\Delta V_{n11} = \frac{C_{gs}T2}{C_{gs}T2 + C_{c1} + C_{f1} + C_o} * (V_{GL} - V_{GH}),$$

where $C_{gs}T2$ represents the first channel capacitance value, C_{c1} represents the capacitance value of the storage capacitor **C1**, C_{f1} represents the capacitance value of the first compensation capacitor **CF1**, and C_o represents other related capacitance values (generally being fixed values).

Since the first scan line **G1** is switched from the low voltage V_{GL} of the low-level signal to the high voltage V_{GH} of the high-level signal, the voltage of the gate of the drive transistor **M0** may be changed by a voltage ΔV_{n12} on the basis of $V_{da}+V_{th}$.

$$\Delta V_{n12} = \frac{C_{f1}}{C_{gs}T2 + C_{c1} + C_{f1} + C_o} * (V_{GL} - V_{GH}).$$

Thus, the amount of change in the voltage of the gate of the drive transistor **M0** is: $\Delta V_{n10} = \Delta V_{n11} + \Delta V_{n12}$. Since the difference between the capacitance value C_{f1} of the first compensation capacitor **CF1** and the first channel capacitance value $C_{gs}T2$ satisfies $0 \pm \Delta C_1$, it may be considered that the capacitance value C_{f1} of the first compensation capacitor **CF1** and the first channel capacitance value $C_{gs}T2$ are equal. Therefore, ΔV_{n11} and ΔV_{n12} may cancel each other out, and ΔV_{n10} may be 0. In this way, after the light emitting stage **T3**, the voltage of the gate of the drive transistor **M0** may be stabilized at $V_{da}+V_{th}$.

Since **EM**=0, the first light emitting control transistor **M5** and the second light emitting control transistor **M6** are both turned on. The turned-on first light emitting control transistor **M5** provides the voltage of the first power end **VDD** to the first electrode of the drive transistor **M0**. The drive transistor **M0** generates the operating current I_{ds} under the action of the voltages of the gate and first electrode of the drive transistor **M0**. $I_{ds} = K(V_{dd} - V_{da})^2$, where K is a structural parameter. The turned-on second light emitting control transistor **M6** turns on the second electrode of the drive transistor **M0** and the first electrode of the light emitting device **L**, so that the light emitting device **L** is driven through the operating current I_{ds} to emit light. Therefore, the operating current generated by the pixel circuit provided by the

embodiment of the present disclosure has nothing to do with the threshold voltage V_{th} of the drive transistor **M0**.

The embodiment of the present disclosure further provides some pixel circuits. The schematic structural diagram 5 of the pixel circuits is shown in FIG. 8A, which is modified in accordance with the implementation in the above-mentioned embodiment. The following only describes the differences between the present embodiment and the above-mentioned embodiment, and the similarities are not repeated 10 here.

In specific implementation, in the embodiment of the present disclosure, as shown in FIG. 8A, the pixel circuit may include: the first reset transistor **M1**, the threshold compensation transistor **M2**, the data writing transistor **M3**, 15 the second reset transistor **M4**, the second light emitting control transistor **M6**, a first reference transistor **M8**, a second reference transistor **M9**, the storage capacitor **C1** and the first compensation capacitor **CFT**, the electrical connection relationship of which is shown in FIG. 8A, which will 20 not be repeated here.

The operation of the pixel circuit provided by the embodiment of the present disclosure will now be described with reference to a signal timing diagram shown in FIG. 8B, taking the structure shown in FIG. 8A as an example. In the 25 following description, the high level is denoted by 1, and the low level is denoted by 0. It should be noted that 1 and 0 are logic levels only to better explain the specific operation of the embodiment of the present disclosure, and not specific voltage values.

30 In the reset stage **T1**, **S1**=1, **G2**=0, **G1**=1, **EM**=1, and **CS**=0.

Since **S1**=1, the first reset transistor **M1** is turned on to provide the signal of the initialization signal line **VINIT** to the gate of the drive transistor **M0** to initialize the gate of the 35 drive transistor **M0**. Since **CS**=0, the second reference transistor **M9** is turned on to provide a signal of a reference signal end **VREF** to the storage capacitor **C1**. Since **G2**=0, the threshold compensation transistor **M2** is turned off. Since **G1**=1, the data writing transistor **M3** and the second reset 40 transistor **M4** are both turned off. Since **EM**=1, both the first reference transistor **M8** and the second light emitting control transistor **M6** are turned off. The voltage of the second electrode of the first compensation capacitor **CFT** is the high voltage V_{GH} of the high-level signal of the first scan line **G1**, and the voltage of the first electrode of the first compensation capacitor **CF1** is the voltage **Vinit** of the initialization signal line **VINIT**.

50 In the data writing stage **T2**, **S1**=0, **G2**=1, **G1**=0, **EM**=1, and **CS**=1.

Since **G1**=0, the data writing transistor **M3** and the second reset transistor **M4** are both turned on. The turned-on data writing transistor **M3** inputs the data voltage V_{da} of the data line **DA** to the storage capacitor **C1**. The turned-on second reset transistor **M4** provides the signal of the initialization signal line **VINIT** to the first electrode of the light emitting device **L** to initialize the first electrode of the light emitting device **L**. Since **G2**=1, the threshold compensation transistor **M2** is turned on. The turned-on threshold compensation transistor **M2** turns on the gate and the second electrode of 55 the drive transistor **M0**, so that the drive transistor **M0** forms a diode electrical connection structure, the gate of the drive transistor **M0** is charged through the first power end **VDD**, and the voltage of the gate of the drive transistor **M0** is made to successfully be $V_{dd}+V_{th}$. The voltage of the second 60 electrode of the first compensation capacitor **CF1** is the low voltage V_{GL} of the low-level signal of the first scan line **G1**, and the voltage of the first electrode of the first compensation capacitor **CF1** is the low voltage V_{GL} of the low-level signal of the first scan line **G1**, and the voltage of the first electrode of the first compensation 65 capacitor **CF1** is the low voltage V_{GL} of the low-level signal of the first scan line **G1**.

tion capacitor **CF1** is $V_{dd}+V_{th}$. Since **S1**=0, the first reset transistor **M1** is turned off. Since **EM**=1, both the first reference transistor **M8** and the second light emitting control transistor **M6** are turned off. V_{dd} is the voltage of the first power end **VDD**.

In the light emitting stage **T3**, **S1**=0, **G2**=0, **G1**=1, and **EM**=0.

Since the second scan line **G2** is switched from the high voltage **VGH** of the high-level signal to the low voltage **VGL** of the low-level signal, the voltage of the gate of the drive transistor **M0** may be changed by a voltage ΔV_{n11} on the basis of $V_{da}+V_{th}$.

$$\Delta V_{n11} = \frac{C_{gsT2}}{C_{gsT2} + C_{c1} + C_{f1} + C_0} * (V_{GL} - V_{GH}),$$

where C_{gsT2} represents the first channel capacitance value, C_{c1} represents the capacitance value of the storage capacitor **C1**, C_{f1} represents the capacitance value of the first compensation capacitor **CF1**, and C_0 represents other related capacitance values (generally being fixed values).

Since the first scan line **G1** is switched from the low voltage **VGL** of the low-level signal to the high voltage **VGH** of the high-level signal, the voltage of the gate of the drive transistor **M0** may be changed by a voltage ΔV_{n12} on the basis of $V_{da}+V_{th}$.

$$\Delta V_{n12} = \frac{C_{f1}}{C_{gsT2} + C_{c1} + C_{f1} + C_0} * (V_{GL} - V_{GH}).$$

Thus, the amount of change in the voltage of the gate of the drive transistor **M0** is: $\Delta V_{n10} = \Delta V_{n11} + \Delta V_{n12}$. Since the difference between the capacitance value C_{f1} of the first compensation capacitor **CF1** and the first channel capacitance value C_{gsT2} satisfies $0 \pm \Delta C_1$, it may be considered that the capacitance value C_{f1} of the first compensation capacitor **CF1** and the first channel capacitance value C_{gsT2} are equal. Therefore, ΔV_{n11} and ΔV_{n12} may cancel each other out, and ΔV_{n10} may be 0. In this way, after the light emitting stage **T3**, the voltage of the gate of the drive transistor **M0** may be stabilized at $V_{da}+V_{th}$.

Since **EM**=0, the first reference transistor **M8** and the second light emitting control transistor **M6** are both turned on. The turned-on first reference transistor **M8** provides the voltage of the reference signal end **VREF** to the storage capacitor **C1**, so that the voltage of the drive transistor **M0** is changed into $V_{dd}+V_{th}+V_{da}$. Therefore, the drive transistor **M0** generates the operating current I_{ds} under the action of the voltages of the gate and first electrode of the drive transistor **M0**. $I_{ds} = K(V_{da})^2$, where K is a structural parameter. The turned-on second light emitting control transistor **M6** turns on the second electrode of the drive transistor **M0** and the first electrode of the light emitting device **L**, so that the light emitting device **L** is driven through the operating current I_{ds} to emit light. Therefore, the operating current generated by the pixel circuit provided by the embodiment of the present disclosure has nothing to do with the threshold voltage V_{th} of the drive transistor **M0** and the voltage of the first power end **VDD**.

An embodiment of the present disclosure also provides a display panel. As shown in FIG. 9, the display panel may include: a plurality of pixel units **PX** disposed in an array in a display region of a base substrate **1000**. Each of the plurality of pixel units **PX** includes a plurality of sub-pixels

spx. Exemplarily, each pixel unit may include a red sub-pixel, a green sub-pixel, and a blue sub-pixel. In this way, red, green and blue may be mixed to achieve color display. Or, each pixel unit may also include a red sub-pixel, a green sub-pixel, a blue sub-pixel, and a white sub-pixel. In this way, red, green, blue and white may be mixed to achieve color display. Of course, in actual applications, light emitting colors of the sub-pixels spx in the pixel units may be designed and determined according to the actual application environment, which is not limited here.

In specific implementation, in the embodiment of the present disclosure, each sub-pixel spx may include the above-mentioned pixel circuit. It should be noted that the structure and operation of the pixel circuit may be described with reference to the above-described embodiment, and will not be described in detail here. The structure of the pixel circuit shown in FIG. 2 is exemplified below.

FIG. 10 is a schematic structural diagram of layout of the pixel circuit in the display panel provided by some embodiments of the present disclosure on the base substrate **1000**. FIGS. 11A to 11G are schematic diagrams of different layers of the pixel circuit provided by some embodiments of the present disclosure. FIG. 12 is a schematic cross-sectional structural diagram of the schematic structural diagram of the layout of the pixel circuit in the display panel shown in FIG. 10 on the base substrate **1000** in a direction AA'. FIG. 13 is a schematic cross-sectional structural diagram of the schematic structural diagram of the layout of the pixel circuit in the display panel shown in FIG. 10 on the base substrate **1000** in a direction BB'. The examples shown in FIGS. 10 to 11G take the pixel circuit in one sub-pixel spx as an example.

Exemplarily, as shown in FIGS. 10, 11A, 12, and 13, a silicon semiconductor layer **600** of the pixel circuit is shown. The silicon semiconductor layer **600** is located on the base substrate **1000**. Exemplarily, the silicon semiconductor layer **600** may be formed by patterning a LTPS material. The silicon semiconductor layer **600** may be used to fabricate active layers of the drive transistor **M0**, the data writing transistor **M3**, the second reset transistor **M4**, the first light emitting control transistor **M5**, and the second light emitting control transistor **M6**. Also, each of the active layers of the drive transistor **M0**, the data writing transistor **M3**, the second reset transistor **M4**, the first light emitting control transistor **M5**, and the second light emitting control transistor **M6** may include a first region, a second region, and a first channel region located between the first region and the second region. For example, FIG. 11A illustrates the first channel region **M0-A** of the drive transistor **M0**, the first channel region **M3-A** of the data writing transistor **M3**, the first channel region **M4-A** of the second reset transistor **M4**, the first channel region **M5-A** of the first light emitting control transistor **M5**, and the first channel region **M6-A** of the second light emitting control transistor **M6**. It should be noted that the above-mentioned first regions and second regions may be conductor regions formed by regions doped with n-type impurities or p-type impurities in the silicon semiconductor layer **600**. Therefore, the first regions and the second regions may be used as source regions and drain regions of the active layers for electrical connection.

Exemplarily, a first gate insulating layer **810** is formed on a side, facing away from the base substrate **1000**, of the silicon semiconductor layer **600**; and used to protect the silicon semiconductor layer **600**. Exemplarily, a thickness of the first gate insulating layer **810** may be 1000-1500 Å. For

example, the thickness of the first gate insulating layer **810** may be 1000 Å, or 1300 Å, or 1500 Å, which is not limited here.

As shown in FIGS. 10, 11B, 12, and 13, a first conductive layer **100** of the pixel circuit is shown. The first conductive layer **100** is disposed on a side, facing away from the base substrate **1000**, of the first gate insulating layer **810** so as to be insulated from the silicon semiconductor layer **600**. The first conductive layer **100** may include: a plurality of first scan lines **G1**, a plurality of light emitting control lines **EM**, a plurality of second reset lines **S2**, gates **M0-G** of the drive transistors **M0**, gates **M3-G** of the data writing transistors **M3**, gates **M4-G** of the second reset transistors **M4**, gates **M5-G** of the first light emitting control transistors **M5**, and gates **M6-G** of the second light emitting control transistors **M6**. The plurality of first scan lines **G1**, the plurality of light emitting control lines **EM** and the plurality of second reset lines **S2** are disposed at intervals.

Exemplarily, a thickness of the first conductive layer **100** may be 2000-3000 Å. For example, the thickness of the first conductive layer **100** may be 2000 Å, or 2500 Å, or 3000 Å, which is not limited here.

Exemplarily, as shown in FIGS. 10 and 11B, one row of sub-pixels corresponds to one first scan line **G1**, one light emitting control line **EM**, and one second reset line **S2**. Exemplarily, the first scan line **G1**, the light emitting control line **EM**, and the second reset line **S2** may extend substantially in a direction **F1** and are disposed in a direction **F2**. The direction **F1** may be a row direction of the sub-pixels, and the direction **F2** may be a column direction of the sub-pixels. Or, the direction **F1** may be the column direction of the sub-pixels, and the direction **F2** may be the row direction of the sub-pixels.

Exemplarily, as shown in FIGS. 10 and 11B, the gate **M3-G** of the data writing transistor **M3** may be a portion where the first scan line **G1** overlaps the silicon semiconductor layer **600**. The gate **M4-G** of the second reset transistor **M4** may be a portion where the second reset line **S2** overlaps the silicon semiconductor layer **600**. The gate **M5-G** of the first light emitting control transistor **M5** may be a first portion where the light emitting control line **EM** overlaps the silicon semiconductor layer **600**. The gate **M6-G** of the second light emitting control transistor **M6** may be a second portion where the light emitting control line **EM** overlaps the silicon semiconductor layer **600**.

Exemplarily, as shown in FIGS. 10 and 11B, for the first scan line **G1** and the data writing transistor corresponding to the same sub-pixel, an orthographic projection of the first scan line **G1** on the base substrate **1000** and an orthographic projection of the active layer of the data writing transistor **M3** on the base substrate **1000** have an overlapping region.

Exemplarily, as shown in FIGS. 10 and 11B, for the data writing transistor **M3**, an active layer of a threshold compensation transistor **M2**, and a compensation conductive part **BD** corresponding to the same sub-pixel, an orthographic projection of the compensation conductive part **BD** on the base substrate **1000** is located between the orthographic projection of the active layer of the data writing transistor **M3** on the base substrate **1000** and an orthographic projection of a third via **GK3** corresponding to the active layer of the threshold compensation transistor **M2** on the base substrate **1000**.

Exemplarily, as shown in FIGS. 10 and 11B, an orthographic projection of the gate **M0-G** of the drive transistor **M0** on the base substrate **1000** is located between the orthographic projection of the first scan line **G1** on the base substrate **1000** and an orthographic projection of the light emitting control line **EM** on the base substrate **1000**.

emitting control line **EM** on the base substrate **1000**. An orthographic projection of the second reset line **S2** on the base substrate **1000** is located on a side, facing away from the gate **M0-G** of the drive transistor **M0**, of the orthographic projection of the light emitting control line **EM** on the base substrate **1000**.

Exemplarily, a first interlayer dielectric layer **820** is formed on a side, facing away from the base substrate **1000**, of the first conductive layer **100**; and used to insulate the first conductive layer **100** from a second conductive layer **200**. Exemplarily, a thickness of the first interlayer dielectric layer **820** may be 1000-1500 Å. For example, the thickness of the first interlayer dielectric layer **820** may be 1000 Å, or 1300 Å, or 1500 Å, which is not limited here.

As shown in FIGS. 10, 11C, 12, and 13, the second conductive layer **200** of the pixel circuit is shown. The second conductive layer **200** is disposed on a side, facing away from the base substrate **1000**, of the first interlayer dielectric layer **820**. The second conductive layer **200** may include a plurality of compensation conductive parts **BD**, a plurality of auxiliary scan lines **FG**, a plurality of auxiliary reset lines **FS**, and storage conductive parts **CC1a** which are disposed at intervals. Exemplarily, an orthographic projection of the storage conductive part **CC1a** on the base substrate **1000** and the orthographic projection of the gate **M0-G** of the drive transistor **M0** on the base substrate **1000** at least partially overlap to form a storage capacitor **C1**. The storage conductive part **CC1a** serves as a first electrode of the storage capacitor **C1**, and the gate **M0-G** of the drive transistor **M0** serves as a second electrode of the storage capacitor **C1**. Exemplarily, the distance between the first electrode and the second electrode of the storage capacitor **C1** may be 1000-1500 Å. For example, the distance between the first electrode and the second electrode of the storage capacitor **C1** may be 1000 Å, or 1200 Å, or 1300 Å, or 1400 Å, or 1500 Å, which is not limited here.

Exemplarily, a thickness of the second conductive layer **200** may be 2000-3000 Å. For example, the thickness of the second conductive layer **200** may be 2000 Å, or 2500 Å, or 3000 Å, which is not limited here.

Exemplarily, as shown in FIGS. 10 and 11C, one row of sub-pixels corresponds to one auxiliary scan line **FG** and one auxiliary reset line **FS**. Exemplarily, the auxiliary scan line **FG** and the auxiliary reset line **FS** may extend in the direction **F1** and be disposed in the direction **F2**.

Exemplarily, as shown in FIGS. 10, 11C, 12, and 13, the sub-pixels may include the compensation conductive parts **BD**. In the same sub-pixel, the compensation conductive part **BD** is electrically connected with the gate **M0-G** of the drive transistor **M0**. For the first scan line **G1** and the compensation conductive part **BD** corresponding to the same sub-pixel, the orthographic projection of the first scan line **G1** on the base substrate **1000** and the orthographic projection of the compensation conductive part **BD** on the base substrate **1000** have a first overlapping region **SQ1**. A first compensation capacitor **CF1** is located in the first overlapping region **SQ1**, and formed by an overlapping portion between the first scan line **G1** and the compensation conductive part **BD**. The first scan line **G1** located in the first overlapping region **SQ1** serves as a second electrode of the first compensation capacitor **CF1**, and the compensation conductive part **BD** located in the first overlapping region **SQ1** serves as a first electrode of the first compensation capacitor **CF1**. Exemplarily, the distance between the first electrode of the first compensation capacitor **CF1** and the second electrode of the first compensation capacitor **CF1** may be 1000-1500 Å. For example, the distance between the

first electrode of the first compensation capacitor CF1 and the second electrode of the first compensation capacitor CF1 may be 1000 Å, or 1200 Å, or 1300 Å, or 1400 Å, or 1500 Å, which is not limited here.

Exemplarily, as shown in FIGS. 10 and 11C, for the first scan line G1 and the compensation conductive part BD corresponding to the same sub-pixel, the orthographic projection of the first scan line G1 on the base substrate 1000 covers the orthographic projection of the compensation conductive part BD on the base substrate 1000.

Exemplarily, a second interlayer dielectric layer 830 is formed on a side, facing away from the base substrate 1000, of the second conductive layer 200; and used to insulate an oxide semiconductor layer 700 from the second conductive layer 200. As shown in FIGS. 10, 11D, 12, and 13, the oxide semiconductor layer 700 of the pixel circuit is shown. The oxide semiconductor layer 700 is located on a side, facing away from the base substrate 1000, of the second interlayer dielectric layer 830. The oxide semiconductor layer 700 includes an active layer of a first reset transistor M1 and the active layer of the threshold compensation transistor M2.

Exemplarily, a thickness of the second interlayer dielectric layer 830 may be 900-1500 Å. For example, the thickness of the second interlayer dielectric layer 830 may be 900 Å, or 1200 Å, or 1500 Å, which is not limited here.

Exemplarily, as shown in FIGS. 10, 11D, 12, and 13, a buffer layer 870 is formed on the side, facing away from the base substrate 1000, of the second interlayer dielectric layer 830; and the oxide semiconductor layer 700 is formed on a side, facing away from the base substrate 1000, of the buffer layer 870. Exemplarily, a material of the buffer layer 870 may be silicon oxide, and a material of the second interlayer dielectric layer 830 may be silicon nitride. Since the features of the material in the oxide semiconductor layer 700 may be affected by direct contact of the oxide semiconductor layer 700 and the silicon nitride, through disposing the buffer layer 870 between the second interlayer dielectric layer 830 and the oxide semiconductor layer 700 according to the embodiment of the present disclosure, the oxide semiconductor layer 700 and the silicon nitride may be prevented from making direct contact, and the silicon nitride is prevented from affecting the features of the material of the oxide semiconductor layer 700. Of course, the material of the second interlayer dielectric layer 830 and the material of the buffer layer 870 may also be both set as silicon oxide.

Exemplarily, a thickness of the buffer layer 870 may be 2000-3000 Å. For example, the thickness of the buffer layer 870 may be 2000 Å, or 2500 Å, or 3000 Å, which is not limited here.

Exemplarily, a thickness of the oxide semiconductor layer 700 may be 300-600 Å. For example, the thickness of the oxide semiconductor layer 700 may be 300 Å, or 500 Å, or 600 Å, which is not limited here.

In addition, each of the active layer of the first reset transistor M1 and the active layer of the threshold compensation transistor M2 may include a third region, a fourth region, and a second channel region located between the third region and the fourth region. For example, FIG. 11D illustrates the second channel region M1-A of the active layer of the first reset transistor M1, and the second channel region M2-A of the active layer of the threshold compensation transistor M2. It should be noted that the third regions and the fourth regions may be conductor regions formed by regions doped with n-type impurities or p-type impurities in the oxide semiconductor layer 700. Therefore, the third

regions and the fourth regions may be used as source regions and drain regions of the active layers for electrical connection.

In addition, as shown in FIGS. 10, 11D, 12, and 13, the active layer of the first reset transistor M1 and the active layer of the threshold compensation transistor M2 may be an integrated structure. Exemplarily, the fourth region M1-D of the active layer of the first reset transistor M1 and the fourth region of the active layer of the threshold compensation transistor M2 are shared.

Exemplarily, a second gate insulating layer 840 is formed on a side, facing away from the base substrate 1000, of the oxide semiconductor layer 700. A third conductive layer 300 is formed on a side, facing away from the base substrate 1000, of the second gate insulating layer 840. As shown in FIGS. 10, 11E, 12, and 13, the third conductive layer 300 of the pixel circuit is shown. The third conductive layer 300 may include a plurality of second scan lines G2 and a plurality of first reset lines S1 disposed at intervals. One row of sub-pixels corresponds to one second scan line G2 and one first reset line S1.

Exemplarily, a thickness of the second gate insulating layer 840 may be 1000-2000 Å. For example, the thickness of the second gate insulating layer 840 may be 1000 Å, or 1500 Å or 2000 Å, which is not limited here.

Exemplarily, a thickness of the third conductive layer 300 may be 2000-3000 Å. For example, the thickness of the third conductive layer 300 may be 2000 Å, or 2500 Å, or 3000 Å, which is not limited here.

As shown in FIGS. 10 and 11E, for the second scan line G2 and the threshold compensation transistor M2 corresponding to the same sub-pixel, the orthographic projection of the active layer of the threshold compensation transistor M2 on the base substrate 1000 and the orthographic projection of the second scan line G2 on the base substrate 1000 have a second overlapping region SQ2. A first part of capacitor of a channel capacitor of the threshold compensation transistor M2 is located in the second overlapping region SQ2, and formed by an overlapping portion between the second scan line G2 and the active layer of the threshold compensation transistor M2. For example, an orthographic projection of the fourth region of the active layer of the threshold compensation transistor M2 on the base substrate 1000 and the orthographic projection of the second scan line G2 on the base substrate 1000 have a second overlapping region SQ2. The first part of capacitor of the channel capacitor of the threshold compensation transistor M2 is located in the second overlapping region SQ2, and formed by an overlapping portion between the second scan line G2 and the fourth region of the active layer of the threshold compensation transistor M2.

Exemplarily, as shown in FIGS. 10 and 11E, for the auxiliary scan line FG and the threshold compensation transistor M2 corresponding to the same sub-pixel, an orthographic projection of the auxiliary scan line FG on the base substrate 1000 and the orthographic projection of the active layer of the threshold compensation transistor M2 on the base substrate 1000 have a third overlapping region SQ3. A second part of capacitor of the channel capacitor of the threshold compensation transistor M2 is located in the third overlapping region SQ3, and formed by an overlapping portion between the auxiliary scan line FG and the active layer of the threshold compensation transistor M2. For example, the orthographic projection of the auxiliary scan line FG on the base substrate 1000 and the orthographic projection of the fourth region of the active layer of the threshold compensation transistor M2 on the base substrate

1000 have a third overlapping region SQ3. The channel capacitor of the threshold compensation transistor M2 further includes the auxiliary scan line FG and the fourth region of the active layer of the threshold compensation transistor M2 in the third overlapping region SQ3. Exemplarily, the third overlapping region SQ3 may overlap the second overlapping region SQ2.

Exemplarily, as shown in FIGS. 10 and 11E, for the threshold compensation transistor M2 and the second scan line G2 corresponding to the same sub-pixel, the orthographic projection of the second scan line G2 on the base substrate 1000 and the orthographic projection of the active layer of the threshold compensation transistor M2 on the base substrate 1000 have the overlapping region. In addition, for the threshold compensation transistor M2 and the auxiliary scan line FG corresponding to the same sub-pixel, the orthographic projection of the auxiliary scan line FG on the base substrate 1000 and the orthographic projection of the active layer of the threshold compensation transistor M2 on the base substrate 1000 have the overlapping region. Further, for the threshold compensation transistor M2 and the second scan line G2 corresponding to the same sub-pixel, the orthographic projection of the second scan line G2 on the base substrate 1000 and an orthographic projection of the channel region of the active layer of the threshold compensation transistor M2 on the base substrate 1000 have an overlapping region. In addition, for the threshold compensation transistor M2 and the auxiliary scan line FG corresponding to the same sub-pixel, the orthographic projection of the auxiliary scan line FG on the base substrate 1000 and the orthographic projection of the channel region of the active layer of the threshold compensation transistor M2 on the base substrate 1000 have an overlapping region. In this way, the threshold compensation transistor M2 may form a double gate structure. As a result, an on-state current of the threshold compensation transistor M2 may be increased, thereby increasing the driving capability of the threshold compensation transistor M2, and improving the transistor features of the threshold compensation transistor M2.

In addition, the orthographic projection of the second scan line G2 on the base substrate 1000 and the orthographic projection of the channel region of the active layer of the threshold compensation transistor M2 on the base substrate 1000 have the overlapping region, and the orthographic projection of the auxiliary scan line FG on the base substrate 1000 and the orthographic projection of the channel region of the active layer of the threshold compensation transistor M2 on the base substrate 1000 have the overlapping region. In this way, light may be shielded through the second scan line G2 and the auxiliary scan line FG, thereby preventing ambient light from being incident on the channel region of the active layer of the threshold compensation transistor M2 through upper and lower sides of the display panel.

Exemplarily, as shown in FIGS. 10 and 11E, for the second scan line G2 and the auxiliary scan line FG corresponding to the same sub-pixel, the orthographic projection of the second scan line G2 on the base substrate 1000 overlaps the orthographic projection of the auxiliary scan line FG on the base substrate 1000. Further, for the second scan line G2 and the auxiliary scan line FG corresponding to the same sub-pixel, the second scan line G2 and the auxiliary scan line FG are electrically connected on a peripheral region of the base substrate 1000.

Exemplarily, as shown in FIGS. 10 and 11E, for the first reset transistor M1 and the first reset line S1 corresponding to the same sub-pixel, an orthographic projection of the first reset line S1 on the base substrate 1000 and an orthographic

projection of the active layer of the first reset transistor M1 on the base substrate 1000 have an overlapping region. In addition, for the first reset transistor M1 and the auxiliary reset line FS corresponding to the same sub-pixel, an orthographic projection of the auxiliary reset line FS on the base substrate 1000 and the orthographic projection of the active layer of the first reset transistor M1 on the base substrate 1000 have an overlapping region. Further, for the first reset transistor M1 and the first reset line S1 corresponding to the same sub-pixel, the orthographic projection of the first reset line S1 on the base substrate 1000 and an orthographic projection of the channel region of the active layer of the first reset transistor M1 on the base substrate 1000 have an overlapping region. In addition, for the first reset transistor M1 and the auxiliary reset line FS corresponding to the same sub-pixel, the orthographic projection of the auxiliary reset line FS on the base substrate 1000 and the orthographic projection of the channel region of the active layer of the first reset transistor M1 on the base substrate 1000 have an overlapping region. In this way, the first reset transistor M1 may form a double gate structure. As a result, an on-state current of the first reset transistor M1 may be increased, thereby increasing the driving capability of the first reset transistor M1, and improving the transistor features of the first reset transistor M1.

In addition, the orthographic projection of the first reset line S1 on the base substrate 1000 and the orthographic projection of the channel region of the active layer of the first reset transistor M1 on the base substrate 1000 have the overlapping region, and the orthographic projection of the auxiliary reset line FS on the base substrate 1000 and the orthographic projection of the channel region of the active layer of the first reset transistor M1 on the base substrate 1000 have the overlapping region. In this way, light may also be shielded through the first reset line S1 and the auxiliary reset line FS, thereby preventing the ambient light from being incident on the channel region of the active layer of the first reset transistor M1 through the upper and lower sides of the display panel.

Exemplarily, as shown in FIGS. 10 and 11E, for the first reset line S1 and the auxiliary reset line FS corresponding to the same sub-pixel, the orthographic projection of the first reset line S1 on the base substrate 1000 overlaps the orthographic projection of the auxiliary reset line FS on the base substrate 1000. Further, for the first reset line S1 and the auxiliary reset line FS corresponding to the same sub-pixel, the first reset line S1 and the auxiliary reset line FS are electrically connected on a peripheral region of the base substrate 1000.

Exemplarily, as shown in FIGS. 10 and 11E, for the first scan line G1, the second scan line G2, and the first reset line S1 corresponding to the same sub-pixel, the orthographic projection of the first scan line G1 on the base substrate 1000 is located between the orthographic projections of the second scan line G2 and the first reset line S1 on the base substrate 1000.

Exemplarily, a third interlayer dielectric layer 850 is formed on a side, facing away from the base substrate 1000, of the third conductive layer; and a fourth conductive layer 400 is formed on a side, facing away from the base substrate 1000, of the third interlayer dielectric layer 850. As shown in FIGS. 10, 11F, 12, and 13, the fourth conductive layer 400 of the pixel circuit is shown. The fourth conductive layer 400 may include a plurality of first connection parts LB1, a plurality of second connection parts LB2, a plurality of third connection parts LB3, a plurality of fourth connection parts LB4, a plurality of fifth connection parts LB5 and a plurality

of initialization signal lines VINIT which are disposed at intervals. A sub-pixel may include one first connection part LB1, one second connection part LB2, one third connection part LB3, one fourth connection part LB4, one fifth connection part LB5, and one initialization signal line VINIT.

Exemplarily, a thickness of the third interlayer dielectric layer 850 may be 5000-6000 Å. For example, the thickness of the third interlayer dielectric layer 850 may be 5000 Å, or 5500 Å, or 6000 Å, which is not limited here.

Exemplarily, a thickness of the fourth conductive layer 400 may be 6000-8000 Å. For example, the thickness of the fourth conductive layer 400 may be 6000 Å, or 7000 Å, or 8000 Å, which is not limited here.

Exemplarily, as shown in FIGS. 10, 11F, 12, and 13, a first end of the first connection part LB1 is electrically connected with the compensation conductive part BD through a first via GK1. A second end of the first connection part LB1 is electrically connected with the gate of the drive transistor through a second via GK2. A third end of the first connection part LB1 is electrically connected with the conductor region of the active layer of the threshold compensation transistor M2 through the third via GK3. In addition, the first via GK1 penetrates the third interlayer dielectric layer 850, the second gate insulating layer 840, and the second interlayer dielectric layer 830. The second via GK2 penetrates the third interlayer dielectric layer 850, the second gate insulating layer 840, the second interlayer dielectric layer 830, and the first interlayer dielectric layer 820. The third via GK3 penetrates the second gate insulating layer 840 and the third interlayer dielectric layer 850.

Exemplarily, as shown in FIGS. 10, 11F, 12, and 13, for the first scan line G1 and the third via GK3 corresponding to the same sub-pixel, the orthographic projection of the first scan line G1 on the base substrate 1000 covers the orthographic projection of the third via GK3 on the base substrate 1000.

Exemplarily, as shown in FIGS. 10, 11F, 12, and 13, the first end and the third end of the first connection part LB1 extend substantially in the same direction, namely the direction F1; and the first end, the second end and the third end of the first connection part LB1 substantially form a "T" shape. It should be noted that in the actual manufacturing process, due to process errors, the first end, the second end, and the third end of the first connection part LB1 may substantially form the "T" shape.

Exemplarily, as shown in FIGS. 10, 11F, 12, and 13, for the same sub-pixel, the orthographic projection of the second scan line G2 on the base substrate 1000 and an orthographic projection of the first connection part LB1 on the base substrate 1000 have a fourth overlapping region SQ4. The fourth overlapping region SQ4 has an auxiliary capacitor formed by an overlapping portion between the second scan line G2 and the first connection part LB1. In addition, a capacitance value of the auxiliary capacitor is substantially Δc1. It should be noted that due to the limitation of process conditions or other factors, the capacitance value of the auxiliary capacitor may not be equal to Δc1, and there may be some deviations. Therefore, the capacitance value of the auxiliary capacitor may satisfy the above-mentioned conditions substantially, which all belong to the protection scope of the present disclosure.

Exemplarily, as shown in FIGS. 10 and 11F, the initialization signal line VINIT is electrically connected with the conductor region of the active layer of the first reset transistor M1 through a fourth via GK4. The fourth via GK4 penetrates the second gate insulating layer 840 and the third interlayer dielectric layer 850.

Exemplarily, as shown in FIGS. 10 and 11F, a first end of the fourth connection part LB4 is electrically connected with a semiconductor layer (for example, the third region) of the active layer of the threshold compensation transistor M2 through a fifth via GK5, and a second end of the fourth connection part LB4 is electrically connected with a semiconductor layer (for example, the second region) of the active layer of the drive transistor M0 through a sixth via GK6. The fifth via GK5 penetrates the second gate insulating layer 840 and the third interlayer dielectric layer 850. The sixth via GK6 penetrates the third interlayer dielectric layer 850, the second gate insulating layer 840, the second interlayer dielectric layer 830, the first interlayer dielectric layer 820, and the first gate insulating layer 810.

Exemplarily, as shown in FIGS. 10, 11G, 12, and 13, an interlayer insulating layer 860 is formed on a side, facing away from the base substrate 1000, of the fourth conductive layer 400; and a fifth conductive layer 500 is formed on a side, facing away from the base substrate 1000, of the interlayer insulating layer 860. As shown in FIGS. 10, 11G, 12, and 13, the fifth conductive layer 500 of the pixel circuit is shown. The fifth conductive layer 500 may include a plurality of data lines DA, a plurality of power lines VD, and a plurality of anode switch parts YZ which are disposed at intervals. A sub-pixel includes one anode switch part YZ, and one column of sub-pixels corresponds to one data line DA and one power line VD.

Exemplarily, a thickness of the interlayer insulating layer 860 may be 15000-30000 Å. For example, the thickness of the interlayer insulating layer 860 may be 15000 Å, or 20000 Å, or 30000 Å, which is not limited here.

Exemplarily, a thickness of the fifth conductive layer 500 may be 6000-8000 Å. For example, the thickness of the fifth conductive layer 500 may be 6000 Å, or 7000 Å, or 8000 Å, which is not limited here.

Exemplarily, as shown in FIGS. 10, 11F, and 11G, for one sub-pixel, the data line DA is electrically connected with the second connection part LB2 through a seventh via GK7, and the second connection part LB2 is electrically connected with the conductor region (for example, the first region) of the active layer of the data writing transistor M3 through an eighth via GK8. The seventh via GK7 penetrates the interlayer insulating layer 860. The eighth via GK8 penetrates the third interlayer dielectric layer 850, the second gate insulating layer 840, the first interlayer dielectric layer 820, and the first gate insulating layer 810. Exemplarily, an orthographic projection of the data line DA on the base substrate 1000 covers an orthographic projection of the second connection part LB2 electrically connected with the data line DA on the base substrate 1000.

Exemplarily, as shown in FIGS. 10, 11F, and 11G, the power line VD is electrically connected with a first end of the third connection part LB3 through a ninth via GK9, a second end of the third connection part LB3 is electrically connected with the conductor region (for example, the first region) of the active layer of the first light emitting control transistor M5 through a tenth via GK10, and a third end of the third connection part LB3 is electrically connected with the storage conductive part CC1a through an eleventh via GK11. That is, the power line VD is electrically connected with a first power end to transmit a voltage to the first power end. The ninth via GK9 penetrates the interlayer insulating layer 860. The tenth via GK10 penetrates the third interlayer dielectric layer 850, the second gate insulating layer 840, the second interlayer dielectric layer 830, the first interlayer dielectric layer 820, and the first gate insulating layer 810.

The eleventh via GK11 penetrates the interlayer insulating layer 860, the third interlayer dielectric layer 850, the second gate insulating layer 840, and the second interlayer dielectric layer 830.

Exemplarily, as shown in FIGS. 10, 11F, and 11G, the first end and the second end of the third connection part LB3 extend substantially in the direction F1; and the first end, the second end and the third end of the third connection part LB3 substantially form an inverted “T” shape. It should be noted that in the actual manufacturing process, due to process errors, the first end, the second end, and the third end of the third connection part LB3 may substantially form the inverted “T” shape.

Exemplarily, as shown in FIGS. 10, 11D, and 11G, for the power line VD and the threshold compensation transistor M2 corresponding to the same sub-pixel, an orthographic projection of the power line VD on the base substrate 1000 and the orthographic projection of the active layer of the threshold compensation transistor M2 on the base substrate 1000 have an overlapping region. Further, for the power line VD and the threshold compensation transistor M2 corresponding to the same sub-pixel, the orthographic projection of the power line VD on the base substrate 1000 covers the orthographic projection of the active layer of the threshold compensation transistor M2 on the base substrate 1000.

Exemplarily, as shown in FIGS. 10, 11D, and 11G, for the power line VD and the first reset transistor M1 corresponding to the same sub-pixel, the orthographic projection of the power line VD on the base substrate 1000 and the orthographic projection of the active layer of the first reset transistor M1 on the base substrate 1000 have an overlapping region. Further, for the power line VD and the first reset transistor M1 corresponding to the same sub-pixel, the orthographic projection of the power line VD on the base substrate 1000 covers the orthographic projection of the active layer of the first reset transistor M1 on the base substrate 1000.

Further, for the power line VD, the threshold compensation transistor M2 and the first reset transistor M1 corresponding to the same sub-pixel, the orthographic projection of the power line VD on the base substrate 1000 covers the orthographic projections of the active layers of the threshold compensation transistor M2 and the first reset transistor M1 on the base substrate 1000.

Exemplarily, as shown in FIGS. 10, 11D, and 11G, for the power line VD, the first via GK1, the second via GK2, the third via GK3, and the third overlapping region SQ3 corresponding to the same sub-pixel, the orthographic projection of the power line VD on the base substrate 1000 has overlapping regions with the first via GK1, the second via GK2, and the third via GK3 respectively. The orthographic projection of the power line VD on the base substrate 1000 does not overlap the fourth overlapping region SQ4.

The anode switch part YZ is electrically connected with the fifth connection part LB5 through a twelfth via GK12. The anode switch part YZ is electrically connected with an anode of a light emitting device through a fourteenth via GK14. The anode switch part YZ is electrically connected with the conductor region (for example, the second region) of the active layer of the second light emitting control transistor M6 through a thirteenth via GK13. The twelfth via GK12 penetrates the interlayer insulating layer 860. The thirteenth via GK13 penetrates the third interlayer dielectric layer 850, the second gate insulating layer 840, the second interlayer dielectric layer 830, the first interlayer dielectric layer 820 and the first gate insulating layer 810. The

fourteenth via GK14 penetrates a flat layer between the fifth conductive layer 500 and a layer where the anode is located.

Exemplarily, a thickness of the flat layer may be 15000 to 30000 Å. For example, the thickness of the flat layer may be 15000 Å, or 20000 Å, or 30000 Å, which is not limited here.

Exemplarily, a parasitic capacitor may include a channel capacitor and a coupling capacitance formed by overlapping of other metal layers, or the parasitic capacitor may also include a channel capacitor. The size of the compensation capacitor in the present application may consider the size of the parasitic capacitor.

Based on the same disclosed concept, an embodiment of the present disclosure also provides a display apparatus including the above pixel circuit provided by the embodiment of the present disclosure. The principle by which the display apparatus solves the problem is similar to that of the afore-mentioned pixel circuit, and therefore the implementation of the display apparatus may be referred to the implementation of the afore-mentioned pixel circuit, which will not be repeated here.

In specific implementation, in the embodiment of the present disclosure, the display apparatus may be any product or component with a display function, such as a mobile phone, a tablet computer, a television, a display, a notebook computer, a digital photo frame, and a navigator. Other essential components of the display apparatus will be apparent to those of ordinary skill in the art and are not described in detail herein, nor should they be construed as limiting the present disclosure.

Although the preferred embodiments of the present disclosure have been described, additional variations and modifications may be made to these embodiments by those skilled in the art once the basic inventive concept is known. Therefore, it is intended that the appended claims be interpreted as including the preferred embodiments and all alterations and modifications that fall within the scope of the present disclosure.

It will be apparent to those skilled in the art that various modifications and variations can be made in the disclosed embodiments without departing from the spirit or scope of the disclosed embodiments. Thus, it is intended that the present disclosure cover the modifications and variations of the disclosure provided they come within the scope of the appended claims and their equivalents.

What is claimed is:

1. A pixel circuit, comprising:
a data writing transistor, wherein a gate of the data writing transistor is electrically connected with a first scan line, a first electrode of the data writing transistor is electrically connected with a data line, a second electrode of the data writing transistor is electrically connected with a first electrode of a drive transistor; wherein a material of an active layer of the data writing transistor is a low temperature poly-silicon material;
a threshold compensation transistor, wherein a gate of the threshold compensation transistor is electrically connected with a second scan line, a first electrode of the threshold compensation transistor is electrically connected with a gate of the drive transistor, a second electrode of the threshold compensation transistor is electrically connected with a second electrode of the drive transistor; wherein a material of an active layer of the threshold compensation transistor is a metal oxide semiconductor material;
a compensation circuit, electrically connected with the gate of the drive transistor and configured to compen-

35

sate for a voltage of the gate of the drive transistor according to a parasitic capacitor; and a light emitting control circuit, electrically connected with a first power end, the first electrode and the second electrode of the drive transistor and a first electrode of a light emitting device, and configured to turn on the first power end and the first electrode of the drive transistor and turn on the second electrode of the drive transistor and the first electrode of the light emitting device under control of a signal of a light emitting control line to drive the light emitting device to emit light;

wherein the parasitic capacitor is a channel capacitor between the gate and the first electrode of the threshold compensation transistor; and a capacitance value of the channel capacitor between the gate and the first electrode of the threshold compensation transistor is a first channel capacitance value, and a difference between a capacitance value of the compensation circuit and the first channel capacitance value is substantially 0.

2. The pixel circuit according to claim 1, wherein the compensation circuit comprises: a first compensation capacitor; and

a first electrode of the first compensation capacitor is electrically connected with the gate of the drive transistor, and a second electrode of the first compensation capacitor is electrically connected with the first scan line;

wherein the capacitance value of the compensation circuit is a capacitance value of the first compensation capacitor.

3. The pixel circuit according to claim 1, wherein the compensation circuit comprises: a first compensation control transistor; and

a gate of the first compensation control transistor is electrically connected with the first scan line, and a first electrode and a second electrode of the first compensation control transistor are electrically connected with the gate of the drive transistor;

wherein a capacitance value of a channel capacitor between the gate and the first electrode of the first compensation control transistor is a second channel capacitance value, a capacitance value of a channel capacitor between the gate and the second electrode of the first compensation control transistor is a third channel capacitance value, and a sum of the second channel capacitance value and the third channel capacitance value is the capacitance value of the compensation circuit.

4. The pixel circuit according to claim 1, wherein the compensation circuit comprises: a second compensation control transistor; and

a gate of the second compensation control transistor is electrically connected with the first scan line, a first electrode of the second compensation control transistor is electrically connected with the gate of the drive transistor, and a second electrode of the second compensation control transistor is in suspended connection; wherein

a capacitance value of a channel capacitor between the gate and the first electrode of the second compensation control transistor is the capacitance value of the compensation circuit.

36

5. The pixel circuit according to claim 1, wherein the compensation circuit comprises: a second compensation capacitor; and

a first electrode of the second compensation capacitor is electrically connected with the gate of the drive transistor, and a second electrode of the second compensation capacitor is electrically connected with the first electrode of the light emitting device;

wherein the capacitance value of the compensation circuit is a capacitance value of the second compensation capacitor.

6. The pixel circuit according to claim 1, wherein the pixel circuit further comprises: a first reset transistor; and

a gate of the first reset transistor is electrically connected with a first reset line, a first electrode of the first reset transistor is electrically connected with an initialization signal line, and a second electrode of the first reset transistor is electrically connected with the gate of the drive transistor;

wherein a material of an active layer of the first reset transistor is a metal oxide semiconductor material.

7. The pixel circuit according to claim 1, wherein the pixel circuit further comprises: a second reset transistor; and

a gate of the second reset transistor is electrically connected with a second reset line, a first electrode of the second reset transistor is electrically connected with an initialization signal line, and a second electrode of the second reset transistor is electrically connected with the first electrode of the light emitting device.

8. The pixel circuit according to claim 1, wherein the pixel circuit comprises: a first light emitting control transistor, a second light emitting control transistor and a storage capacitor;

a gate of the first light emitting control transistor is electrically connected with the light emitting control line, a first electrode of the first light emitting control transistor is electrically connected with the first power end, and a second electrode of the first light emitting control transistor is electrically connected with the first electrode of the drive transistor;

a gate of the second light emitting control transistor is electrically connected with the light emitting control line, a first electrode of the second light emitting control transistor is electrically connected with the second electrode of the drive transistor, and a second electrode of the second light emitting control transistor is electrically connected with the first electrode of the light emitting device; and

a first electrode of the storage capacitor is electrically connected with the first power end, and a second electrode of the storage capacitor is electrically connected with the gate of the drive transistor.

9. A display panel, comprising:

a base substrate, comprising a plurality of sub-pixels, wherein each of the plurality of sub-pixels comprise a pixel circuit, and the pixel circuit comprises a first compensation capacitor and a drive transistor;

a first conductive layer, arranged on the base substrate, and comprising a first scan line and a gate of the drive transistor; wherein one row of sub-pixels corresponds to one first scan line;

a first interlayer dielectric layer, arranged on a side, facing away from the base substrate, of the first conductive layer; and

a second conductive layer, arranged on a side, facing away from the base substrate, of the first interlayer

dielectric layer; wherein the second conductive layer comprises compensation conductive parts; wherein the plurality of sub-pixels comprise the compensation conductive parts; for a same sub-pixel, a compensation conductive part is electrically connected with the gate of the drive transistor; for the first scan line and the compensation conductive part corresponding to the same sub-pixel, an orthographic projection of the first scan line on the base substrate and an orthographic projection of the compensation conductive part on the base substrate have a first overlapping region; and the first compensation capacitor is arranged in the first overlapping region, and the first compensation capacitor is formed by an overlapping portion between the first scan line and the compensation conductive part.

10. The display panel according to claim 9, wherein for the first scan line and the compensation conductive part corresponding to the same sub-pixel, the orthographic projection of the first scan line on the base substrate covers the orthographic projection of the compensation conductive part on the base substrate. 20

11. The display panel according to claim 9, wherein the 25 pixel circuit further comprises a threshold compensation transistor;

wherein the display panel further comprises:
 a second interlayer dielectric layer, arranged on a side, facing away from the base substrate, of the second conductive layer;
 an oxide semiconductor layer, arranged on a side, facing away from the base substrate, of the second interlayer dielectric layer; wherein the oxide semiconductor layer comprises an active layer of the threshold compensation transistor;

- a second gate insulating layer, arranged on a side, facing away from the base substrate, of the oxide semiconductor layer; and
- a third conductive layer, arranged on a side, facing away from the base substrate, of the second gate insulating layer, and comprising a second scan line, wherein one row of sub-pixels corresponds to one second scan line; wherein for the second scan line and the threshold compensation transistor corresponding to the same sub-pixel, an orthographic projection of the active layer of the threshold compensation transistor on the base substrate and an orthographic projection of the second scan line on the base substrate have a second overlapping region; and

a first part of capacitor of a channel capacitor of the threshold compensation transistor is arranged in the second overlapping region, and the first part of capacitor is formed by an overlapping portion between the second scan line and the active layer of the threshold compensation transistor.

12. The display panel according to claim 11, wherein the second conductive layer further comprises an auxiliary scan line;

one row of sub-pixels corresponds to one auxiliary scan line; for the auxiliary scan line and the threshold compensation transistor corresponding to the same sub-pixel, an orthographic projection of the auxiliary scan line on the base substrate and the orthographic projection of the active layer of the threshold compensation transistor on the base substrate have a third overlapping region; and

a second part of capacitor of the channel capacitor of the threshold compensation transistor is arranged in the third overlapping region, and the second part of capacitor is formed by an overlapping portion between the auxiliary scan line and the active layer of the threshold compensation transistor; wherein for the second scan line and the auxiliary scan line corresponding to the same sub-pixel, the orthographic projection of the second scan line on the base substrate overlaps the orthographic projection of the auxiliary scan line on the base substrate.

13. The display panel according to claim 11, wherein the display panel further comprises:

a third interlayer dielectric layer, arranged on a side, facing away from the base substrate, of the third conductive layer; and

a fourth conductive layer, arranged on a side, facing away from the base substrate, of the third interlayer dielectric layer and comprising a first connection part;

wherein a first end of the first connection part is electrically connected with the compensation conductive part through a first via, and a second end of the first connection part is electrically connected with the gate of the drive transistor via a second via;

the first via penetrates the third interlayer dielectric layer, the second gate insulating layer and the second interlayer dielectric layer; and

the second via penetrates the third interlayer dielectric layer, the second gate insulating layer, the second interlayer dielectric layer, and the first interlayer dielectric layer.

14. The display panel according to claim 13, wherein a third end of the first connection part is electrically connected with a conductor region of the active layer of the threshold compensation transistor through a third via; and

the third via penetrates the second gate insulating layer and the third interlayer dielectric layer; wherein for the first scan line and the third via corresponding to the same sub-pixel, the orthographic projection of the first scan line on the base substrate covers an orthographic projection of the third via on the base substrate;

substance, wherein the first end and the third end of the first connection part extend substantially in a same direction; and

the first end, the second end and the third end of the first connection part substantially form a T shape.

wherein an auxiliary capacitor is disposed in the fourth overlapping region;

the auxiliary capacitor is formed by an overlapping portion between the second scan line and the first connection.

a capacitance value of the auxiliary capacitor is substantially Δc_1 .

16. The display panel according to claim 13, further comprising:

an interlayer insulating layer, arranged on a side, facing away from the base substrate, of the fourth conductive layer; and

a fifth conductive layer, arranged on a side, facing away from the base substrate, of the interlayer insulating layer, and comprising a data line and a power line;

39

wherein one column of sub-pixels corresponds to one data line and one power line;
 wherein for the power line and the threshold compensation transistor corresponding to the same sub-pixel, an orthographic projection of the power line on the base substrate and the orthographic projection of the active layer of the threshold compensation transistor on the base substrate have an overlapping region;
 wherein for the power line, the first via, the second via, the third via, and the third overlapping region corresponding to the same sub-pixel:
 the orthographic projection of the power line on the base substrate has overlapping regions with the first via, the second via, and the third via respectively; and
 the orthographic projection of the power line on the base substrate does not overlap the fourth overlapping region.

17. The display panel according to claim 16, wherein the pixel circuit further comprises a first reset transistor; the oxide semiconductor layer further comprises an active layer of the first reset transistor;
 the third conductive layer further comprises a first reset line;
 one row of sub-pixels corresponds to one first reset line; and
 for the first reset transistor and the first reset line corresponding to the same sub-pixel, an orthographic projection of the first reset line on the base substrate and an orthographic projection of the active layer of the first reset transistor on the base substrate have an overlapping region;
 wherein for the power line and the first reset transistor corresponding to the same sub-pixel, the orthographic projection of the power line on the base substrate and the orthographic projection of the active layer of the first reset transistor on the base substrate have an overlapping region;

40

wherein for the first scan line, the second scan line, and the first reset line corresponding to the same sub-pixel, the orthographic projection of the first scan line on the base substrate is arranged between the orthographic projection of the second scan line on the base substrate and the orthographic projection of the first reset line on the base substrate.

18. The display panel according to claim 17, wherein the pixel circuit further comprises a data writing transistor; wherein the display panel further comprises:

a silicon semiconductor layer, arranged between the first conductive layer and the base substrate; wherein the silicon semiconductor layer comprises an active layer of the data writing transistor; and
 a first gate insulating layer, arranged between the first conductive layer and the silicon semiconductor layer; wherein for the first scan line and the data writing transistor corresponding to the same sub-pixel, the orthographic projection of the first scan line on the base substrate and an orthographic projection of the active layer of the data writing transistor on the base substrate have an overlapping region;
 wherein for the data writing transistor, the active layer of the threshold compensation transistor, and the compensation conductive part corresponding to the same sub-pixel:
 the orthographic projection of the compensation conductive part on the base substrate is arranged between the orthographic projection of the active layer of the data writing transistor on the base substrate and an orthographic projection of a third via corresponding to the active layer of the threshold compensation transistor on the base substrate.

19. A display apparatus, comprising the display panel according to claim 9.
